UNITED STATES PATENT OFFICE

EARL A. BESSOM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY

HEEL-SEAT FITTING MACHINE

Application filed May 29, 1931. Serial No. 540,990.

This invention relates to machines for use in the manufacture of shoes and is illustrated herein as embodied in a machine for fitting the heel portions of the soles of shoes for the 5 reception of heels.

During the manufacture of shoes to which wood heels, for example, are to be attached, it is customary to reduce the rear portion of the sole of each shoe for receiving the attaching 10 face of a heel and also to form a pair of shoulders, one at each end of the heel breast line, extending transversely of the sole and against which the breast of the heel abuts when the heel is correctly positioned upon the shoe. 15 This operation is commonly known as heel-seat fitting.

In fitting the heel seats of shoes, it is important that the reduced heel-seat portion of the sole, which is often referred to as a 20 tongue, shall substantially fill up the cavity of the attaching face of the heel in order to serve as a solid support upon which the heel may be attached. Care must be taken, however, to remove from the sole an amount of 25 material sufficient to permit the rim of the attaching face of the heel to be pressed snugly against the overlasted counter portion of the shoe in order to cause a merging of the lines of the counter portion of the shoe and 30 the side of the heel and thereby to produce a shoe which is neat in appearance where the heel joins the shoe upper. It is also desirable that the heel-breast-receiving shoulders against which the breast of the heel abuts 35 shall be formed to a shape complementary to the portion of the breast surface of the heel against which they are to engage and shall also be properly positioned upon the sole in order that when the heel is attached to the 40 shoe in its desired position the heel-breast-receiving shoulders will be in abutting relation with the breast of the heel.

It is an object of this invention to provide an improved machine for quickly and 45 accurately fitting the heel seats of shoes of any and all types. Accordingly, the illustrated machine, which in its general organization is similar in many respects to the machine disclosed in United States Letters 50 Patent No. 1,837,399, granted December 22,

1931 on an application filed in my name, is thoroughly effective in fitting the heel seats of welt, McKay, turn and compo shoes and even of some stitchdowns.

In order accurately to fit the heel-seat portion of a shoe for receiving a wood heel, the sole should be properly positioned in the machine, both widthwise and lengthwise, relatively to the trimming instrumentalities of the machine and should be held in such position during the trimming operation. The shoe to be operated on by the machine disclosed in said United States Letters Patent No. 1,837,399, as in the illustrated machine, is positioned lengthwise by a back gage. A 55 shoe the heel-seat portion of the sole of which is fitted by the use of the machine disclosed in that application, however, is positioned widthwise by crease plates, constructed and arranged to enter the rand crease of the shoe 60 at opposite sides of the shoe, and engaging the sole-attaching stitches which in welt, McKay and turn shoes extend rearwardly of the breast line, even if for only a short distance, and are located at opposite sides of 65 and at substantially equal distances from the median plane of the sole.

The crease plates of the machine disclosed in said United States Letters Patent No. 1,837,399 and in an application for United States Letters Patent Serial No. 170,881, filed February 25, 1927, in the name of Harry A. Ballard, in addition to centering the soles of the shoes in the machines are designed to 70 control the path of movement of a rotating cutter, which is moved in a U-shaped path peripherally of the heel seat of the shoe and thereby trims the rear part of the sole to provide a tongue or reduced heel-seat portion 75 of the sole having a heel-contacting surface substantially complementary to the attaching face of the heel. This cutter is hereinafter spoken of as a "back cutter" to distinguish it from the cutter which makes the heel-breast-receiving shoulders.

In operating upon compo shoes there are 80 no lines of stitches which may be utilized as above described for centering the sole of the shoe and the sole-attaching cement is not 85 ordinarily extended to the rear of the heel 90 95 100

breast line. In order, therefore, to center such shoes or to center shoes of any type if the heel-seat fitting is performed before the permanent sole attachment and while the 5 soles are held only by the sole laying fastenings, as is sometimes done in the manufacture of McKay shoes, the shoes must be positioned relatively to the median plane of the machine by centralizing members which 10 engage other parts of the shoe. In order that the mechanism for centralizing the shoe will be effective it should be located away from the paths of movement of the cutters which perform the fitting operation, should rigidly 15 hold the shoe in position while being operated upon, and should be constructed and arranged to position the soles of both right and left shoes so that the median or central plane of the soles of the shoes will be positioned in the 20 median or central plane of the machine and will therefore be symmetrical with respect to the paths of movement of the cutters of the machine.

In a machine in which the back cutter is 25 constructed and arranged to be moved peripherally of the heel seat to form a tongue or a reduced heel-seat portion of the sole which will accurately fit the attaching face of a heel to be applied to the shoe and in 30 which the cutter is guided in a path controlled by the setting of crease plates as above described, it is desirable not only accurately to centralize the shoe but also to position the crease plates in the same location 35 relatively to the shoe that they would assume when centering a sole of a shoe secured to the shoe upper by stitching. Such a heel-seat fitting machine will operate effectively on both cemented and sewed sole 40 work as well as on shoes the soles of which have been laid but not yet stitched.

With the above object in view and in order to cooperate with the back gage in positioning the soles of shoes in the machine, the illustrated machine, in accordance with a feature 45 of the invention, is provided with a movable gage which is constructed and arranged to engage the opposite sides of the rear part of the counter portion of the shoe 50 in combination with centralizing or clamping members mounted for equal and opposite movement toward and away from the median plane of the machine and shaped and arranged to engage opposite sides of the 55 shoe as the gage is moved rearwardly under pressure applied through the shoe, the gage cooperating with the centralizing or clamping members to position the shoe widthwise in the machine.

60 The centralizing and clamping members which, as illustrated, are mounted for equal and opposite movement and engage opposite sides of the shoe upper, are designed properly to position the soles of both right and 65 left shoes. In accordance with another fea-

ture of the invention, these members comprise shoe-engaging parts mounted for pivotal movement and constructed and arranged to tilt upon contact with the shoe upper, the degree of tilting depending upon the inclination of the shoe upper to the median plane of the shoe at the point of contact. This tilting of the shoe-engaging parts, which may be geared together and have their shoe-contacting portions normally positioned at 70 equal and opposite distances from the median plane of the machine when these portions are out of contact with the shoe upper, causes one of the parts to shorten more than the other because of the difference in the curvature of the two sides of the shoe at the 75 points of contact, with the effect that a point equidistant from the points of contact with the shoe upper will move to one side of the median plane of the machine when positioning a right shoe and will move an equal distance to the opposite side of the median plane of the shoe when positioning a left shoe. The median planes of the soles of 80 both right and left shoes positioned by the above-mentioned members, however, will lie substantially in the median plane of the machine, and will, therefore, be symmetrical with respect to the paths of movement of the 85 cutters.

In order, when operating on shoes the soles of which are not attached by stitching, to locate the crease plates in the same position that they would occupy were they centralizing a corresponding shoe having a 90 sewed sole, and in accordance with another feature of the invention, the arms of the centralizing and clamping members of the illustrated machine carry stops which, when the shoe has the median plane of its sole 95 positioned in the median plane of the machine, are engaged by the crease plates which are moved into operative position against the stops and, by appropriate mechanism, lock the centralizing or clamping members 100 against movement.

In addition to varying the shape of the horseshoe-shaped path of the back cutter which moves peripherally of the heel seat portion of the sole to trim off the surplus material thereby forming a rearwardly extending tongue portion, the crease plates, in accordance with another feature of the invention, are designed automatically to vary the path of a cutter mounted for movement 115 transversely from one edge of the sole to the other to form heel-breast-receiving shoulders upon the sole and for winging out fillets from the sole rearwardly of the shoulder, in order that the width of the base of the tongue 120 will correspond in width to the forward portion of the tongue formed by the back cutter.

In fitting the heel seats of shoes the crease plates of the heel-seat fitting machine should enter between the sole and the overlasted por- 125

tion of the shoe upper at least as far forward as the heel-breast line of the sole in order properly to support the sole and to protect the shoe upper. These plates, however, when operating on compo shoes, the soles of which are attached merely by an adhesive, should not enter the shoe forwardly of that line or they may break the adhesive bond by which the sole is attached to the shoe. In order therefore, that when operating on shoes of different sizes the forward edges of the crease plates will terminate substantially at the breast line of the shoe, and in accordance with a further feature of this invention, the illustrated machine is provided with crease plate members which, together with the shoulder-forming cutter, are mounted for adjustment lengthwise of the positioned shoe to a position determined by a heel gage such as described in the above-mentioned application for United States Letters Patent Serial No. 170,881 and in said United States Letters Patent No. 1,837,399.

Shoulders for receiving the breasts of Louis or Cuban heels may be cut on shoes of a given size by the use of the illustrated machine, without adjusting the position of the shoe lengthwise in the machine. To this end the shoulder-forming cutter is a guide bar which is positioned by the heel gage above mentioned and which, in combination with other mechanism carried by the bar, guides the shoulder-forming cutter in varying paths, dependent upon the style and size of the shoe, across the sole of the shoe. In order to change from one style of heel to another and in accordance with another feature of the invention, the mechanism of the illustrated machine for guiding the shoulder-forming cutter across the sole comprises a latch slide which may be set in one position for causing the cutter-guiding mechanism to move the cutter heightwise of the sole as it moves transversely across the sole for forming shoulders shaped and positioned for engaging the projecting lip of the breast of a Louis heel and which may be set in another position to cause the cutter-guiding mechanism to move the cutter lengthwise of the heel further to the rear, as well as heightwise of the sole, upon movement transversely across the sole thereby forming shoulders curved in the plane of the sole and shaped to engage the breast portion of a Cuban heel.

As above stated, the guide bar upon which the shoulder-forming cutter is moved across the sole is not adjusted lengthwise of the sole of the shoe when the operator changes from Cuban to Louis heel work and in order that the crease plates shall extend to but not forwardly of the breast line of the heel when operating on both Cuban and Louis heel work and in accordance with a further feature of the invention, the crease plates may be adjusted relatively to the guide bar and the

cutter to forward and rearward positions for setting the machine to operate upon Louis and Cuban work respectively.

In order to prevent the sole supported by the crease plates from being picked up by the cutter during the shoulder-forming operation and in accordance with still another feature of the invention, the illustrated machine is provided with a holddown supported for movement with and ahead of the rotary shoulder-forming cutter and pivotally mounted for movement about the axis of rotation of the cutter, the arrangement being such that the holddown progressively presses a portion of the sole ahead of the cutter toward the last or the jack by which the shoe is carried by reason of the frictional drag between the sole and the cutter. The illustrated hold-down is constructed and arranged to ride up the tread face of the sole as the cutter is moved transversely across the sole toward the median plane of the sole and also to rise relatively to the cutter as the sole increases in thickness. It has been found to be unnecessary to hold down the sole after the cutter reaches a position at which it starts to rise heightwise of the sole and in order therefore to retain the holddown in its raised position during the remainder of the shoulder-forming operation, thereby lessening the power consumed, the illustrated machine is provided with a pawl and ratchet arrangement for retaining the holddown in raised position until the cutter arrives back at its starting point when the holddown is released and is urged toward the crease plates.

In order to guide the rotary back cutter in a horseshoe-shaped path to reduce the heel seat portion of the sole, the shaft, upon which the cutter is mounted, does not move within a guideway formed in templet plates of the machine as disclosed in the United States Letters Patent No. 1,661,391, granted March 6, 1928 on an application filed in the name of William C. Stewart, and has also disclosed in the above-mentioned United States Letters Patent No. 1,837,399, but in accordance with another feature of this invention, the illustrated machine is provided with a circular plate having cam rolls constructed and arranged to travel in a horseshoe-shaped guideway formed in the templets which, as above explained, are mounted for adjustment toward and away from each other with the crease plates, and a rotary cutter the shaft of which passes through the plate and is constrained for movement around the rear portion of the sole as the cam rolls carried by the plate are moved around the guideway. By guiding the shaft of the rotary back cutter indirectly through the circular plate, as distinguished from guiding the rotary cutter shaft by slots cut through templet plates, the machine can be made to reduce the heel seat portion of the sole of a shoe to an ex-

tremely narrow tongue, if desired, without necessitating such a design of any of the parts of the machine, particularly the parts which guide the cutter in the horseshoe-shaped path, as might impair their strength.

In order to permit the back cutter which moves in the horseshoe-shaped path to move farther forward of the machine when operating upon Louis work than when operating on Cuban work and in accordance with a further feature of the invention, the guide bar upon which the shoulder-forming cutters are mounted carries a gage which is pivotally mounted for adjustment into either of two positions and has two gaging faces located at unequal distances from the point about which the gage is pivoted, the arrangement being such that either of the gaging faces which limits the movement of the back cutter forwardly of the machine may be disposed toward the rear portion of the machine according to whether it is desired to fit the heel-seat portion of the shoe for receiving a Louis or a Cuban heel.

To provide for adjusting the rotary back cutter axially of its shaft relatively to the crease plates and in accordance with another feature of the invention, a sleeve or bushing mounted upon the shaft and secured against axial movement relatively to the shaft has a spur gear affixed thereto and shaped and arranged to mesh with a worm carried by a member which supports the bushing and is in threaded relation therewith, the arrangement being such that the operator may rotate the worm and thereby rotate the bushing relatively to the member for adjusting the rotary cutter toward and away from the crease plates.

These and other features of the invention will now be described with reference to the accompanying drawings, in which

Figs. 1 and 2 are front and plan views, respectively, of the illustrated heel seat fitting machine, certain parts of which have been broken away more clearly to show the construction of the machine;

Fig. 4 is a horizontal sectional view of the machine taken along line IV—IV of Fig. 3;

Fig. 5 is an enlarged plan view of a portion of the top of the machine, parts having been broken away to illustrate portions of mechanism for guiding a rotary back cutter which is designed to reduce the rear portion of a sole peripherally of the sole;

Fig. 6 is a side view of heel gaging apparatus as viewed while looking in the direction indicated by arrows VI—VI of Fig. 2;

Fig. 7 is a vertical sectional view of the rear portion of the machine as viewed while looking in the direction of arrows VII—VII of Fig. 2;

Fig. 8 is an enlarged plan view, partly

broken away, of mechanism for positioning a shoe widthwise and lengthwise in the above machine preparatory to operating upon the sole;

Fig. 9 is a side view of one of the heel centralizing and clamping members illustrated in Fig. 8 while looking in the direction indicated by arrows IX—IX of that figure;

Fig. 10 shows a transverse sectional view of a shoe mounted upon a last and also shows the relative positions of shoe-contacting parts of the centralizing and clamping members and the shoe when the shoe has been centralized in the machine;

Fig. 11 is a perspective view of the rear portion of an inverted shoe as it comes to the machine for having its heel seat fitted;

Fig. 12 is a perspective view illustrating the shoe shown in Fig. 11 after the rear portion of the sole of that shoe has been trimmed around its peripheral portion by the back cutter to reduce or to tongue the rear portion of the sole;

Fig. 13 is a perspective view corresponding to Fig. 12 but showing the shoe after heel-breast-receiving shoulders have been formed upon the shoe to complete the heel-seat fitting operation;

Fig. 14 is a plan view of mechanism for controlling the movement of the rotary cutter which forms heel-breast-receiving shoulders upon the sole of the positioned shoe, parts of the casing in this view having been broken away in order clearly to illustrate the interior construction of this mechanism;

Fig. 15 is a perspective view of the mechanism illustrated in Fig. 14 as seen from above looking in the direction indicated by the arrow XV of Fig. 14;

Fig. 16 is a sectional view of the mechanism for forming the heel-breast-receiving shoulders, this view having been taken along the line XVI—XVI of Fig. 14;

Fig. 17 is a rear view of the cutter and portions of the mechanism for forming the heel-breast-receiving shoulders, as seen while looking in the direction of arrows XVII—XVII of Fig. 16 and also illustrates the relative position of a shoe, the cutter, a sole-supporting crease plate, and a sole holdown as the cutter starts to trim the sole upon movement transversely across the same;

Fig. 18 is a view similar to that shown in Fig. 17 but showing the relative positions of the parts illustrated in that figure after the cutter has trimmed the full thickness of the sole for a short distance and is about to rise as it moves transversely of the sole;

Fig. 19 is an end view of the mechanism illustrated in Fig. 17 while looking along the axis about which the cutter is rotated, the cutter having been removed to illustrate clearly the construction of the sole holdown which travels in front of the cutter as the cutter moves across the sole; and

Fig. 20 is a diagrammatic view illustrating the projections of the paths of movement of the rotary shoulder-forming cutter upon the sole while operating upon Cuban and Louis work and also illustrating the outlines of corresponding Cuban and Louis heels in relation to said projections.

The illustrated heel-seat fitting machine is of the same general type as the machine disclosed in the above-mentioned United States Letters Patent No. 1,661,391, and more closely resembles the machine disclosed in the above-mentioned United States Letters Patent 1,837,399. The illustrated machine, like each of the machines just referred to, has a main frame 30 (Fig. 3) comprising leg castings 32 for supporting a bed casting 34 (Fig. 1), provided at its central part with a recessed portion 36 (Figs. 1 and 3) into which the shoe to be operated upon is introduced.

In order to cooperate with other members, which will presently be described, in holding the shoe during the heel-seat fitting operation and for assisting the operator in presenting the shoe to the machine, the machine is provided with a shoe support 38 substantially identical with the support disclosed in said United States Letters Patent No. 1,837,399, and comprises a last pin 40 mounted for lateral sliding movement in a T-shaped slot 42 (Fig. 3) formed in the top of hollow post 44 which is in telescopic relation with a lower post 46 pivoted to the main frame at 48. The hollow post 44 is normally held in a raised position relatively to the lower post 46 by a spring 50 (Fig. 3) housed in the hollow post 44 and having its upper and lower ends bearing upon the inside of the hollow post 44 and against the lower post respectively.

In order to serve as a support for the sole of the shoe as well as to guard the shoe upper from being cut during the heel-seat fitting operation, the machine is provided with crease plates 52 which enter the rand crease of the shoe, the shoe being positioned widthwise and lengthwise in the machine upon the support 38 by centralizing members 54 and a back stop or gage 55 respectively. As in the machine disclosed in United States Letters Patent No. 1,837,399, after the shoe is positioned and securely held in the machine, a rotary back cutter 56, which is supported for rotation upon a shaft 58 disposed at substantially right angles to the sole of the positioned shoe, moves around the rear peripheral part of the sole for trimming a tongue or reduced heel-seat portion 60 (Fig. 12) having a beveled marginal portion 62. To complete the heel-seat fitting operation after having cut the tongue 60 in the sole, the machine is provided with a rotary cutter 64 which is mounted for movement transversely across the sole for forming heel-breast-receiving shoulders 66 (Fig. 13) and for wing-

ing out fillets 68 (Fig. 12) located immediately rearward of the shoulders, in order to form continuations of the tongue 60 which extend to the shoulders 66 and form with the shoulders clean-cut corners. The shoulders 66 which may be said to constitute a heel-breast-receiving abutment are illustrated as separated by the full thickness of the sole. It will be understood, however, that when the tongue 60 is very narrow, the heel-breast-receiving abutment extends from one side of the tongue to the other. A heel seat shaped by the use of the illustrated machine and as shown in Fig. 13 will accurately fit the attaching face of a heel which is to be applied to the shoe and the heel-breast-receiving shoulders will conform to the shape of the breast of the heel, thus providing a shoe which is neat in appearance where the heel joins the shoe upper and a heel seat which will engage substantially the entire attaching face of the heel for effectively supporting the heel.

As above stated, in fitting the heel seats of soles of compo shoes, as distinguished from the operation of fitting the heel seats of soles which are sewed to shoe uppers by lines of stitches, it is important that the sole-supporting crease plates 52 shall not enter the rand crease of the shoe forwardly of the breast line 70 (Figs. 11, 12, and 13) of the sole and thus disturb the adhesive bond by which the sole is attached to the shoe upper. Accordingly, in the illustrated machine provision is made for adjusting the crease plates 52 between the operations of fitting the heel seats of soles of different sizes in order that the forward edges 72 of the crease plates 52 will terminate substantially at the breast lines 70 of the soles of different sizes of shoes fitted in the machines.

Another difference between the operations of fitting the heel seats of the above-mentioned sewed and adhesively secured soles in machines of the general type disclosed in said United States Letters Patent No. 1,837,399 is that, in order to centralize a sewed sole of a shoe widthwise in the machine, the crease plates 52, which are mounted for equal and opposite movements and are located at equal distances from an imaginary vertical median plane 74 (Fig. 1) centralized relatively to the paths of movement of the back cutter 56 and the cutter 64 and which will be referred to as a central or median plane, enter the rand crease until they strike the line of sole-attaching stitches located at substantially equal distances from the median plane of the sole, while in operating upon the sole of a compo shoe another device for centering the sole widthwise as well as for positioning the crease plates, the position of which control the paths of movement of the cutters 66, 64, should be provided in

in order to avoid disturbing the cement by which the soles are attached.

The machine disclosed in the above-mentioned United States Letters Patent No. 1,837,399 is illustrated with reference to the fitting of soles secured by stitching to shoe uppers. In that machine movable templets are constrained for movement with crease plates and correspond to templets 76 of the illustrated machine, having a horseshoe-shaped cam way or guideway 78 for controlling the movement of the back cutter 56, which trims material from the rear portion of the sole of the shoe to form the tongue 60, the size and shape of which is determined as above stated by the operative position of the crease plates 52. In the illustrated machine not only is the horseshoe-shaped path of the back cutter 56 controlled by the position of the crease plates 52 but also the path of movement of the shoulder-forming cutter 64 is controlled by the crease plates through mechanism which will later be described in detail.

It is important that when the sole of a compo shoe is centralized in the machine by mechanism which will later be described, the crease plates 52 shall be moved toward each other to the same extent they would be moved if they were centralizing in the machine a sole attached to a corresponding shoe by lines of stitches. The illustrated machine which is designed to meet these conditions as will later appear may be used effectively and interchangeably for fitting the heel seats of shoes, the soles of which have been sewed or cemented to the shoe uppers.

As above stated, in fitting the heel seats of compo shoes, the crease plates 52 which support the sole against the action of the cutters 56 should extend to the breast line 70 of the sole of the shoe being fitted but should not extend forwardly of that line. Accordingly, the crease plates 52 are arranged so that they may be adjusted forwardly and rearwardly of the machine together with the shoulder-forming cutter 64, and relatively to the back stop 55 by a heel gage 80 controlled by a heel 82, which is to be applied to the shoe, or a heel identical with that heel.

The mechanism for adjusting a guide bar 84, along which the heel-shoulder-forming cutter 64 is moved transversely across the sole, relatively to the back stop 55 for forming the heel-breast-receiving shoulders 66 at their proper positions lengthwise of the sole, will be described later and is fully disclosed in the above-mentioned United States Letters Patent No. 1,837,399.

60 Crease plate construction

Secured to the bed casting 34 of the machine is a bed plate 86 (Fig. 1) consisting of top and bottom parts 88 and 90, respectively, 65 screwed together and having a recessed por-

tion 92 (Fig. 4) shaped generally to conform to the recessed portion 36 of the bed plate 34. The plate 90 (Fig. 1) supports a pair of arcuate plates 94 which are partially included between the parts 88 and 90 of the bed plate 86 and each of which has an arcuate groove 96 (Fig. 4) for receiving a correspondingly-shaped arcuate flange 97 (Fig. 1) of the top part 88 of the bed plate 86. The arcuate plates 94 are mounted for movement through mechanism, which will be described later, in arcuate paths along their corresponding arcuate flanges 97. Secured to the central parts of the inner portions of each of the arcuate plates 94 (Fig. 4) are back plates 98 having their forward inner edges 100 contacting with each other and their opposing sides diverging rearwardly from the point of contact. The back plates 98 are constructed and arranged to enter the rear portion of the rand crease of the shoe positioned in the machine, the mounting of the arcuate plates 94 and the back plates 98 being such that when the arcuate plates 94 are swung along their respective arcuate flanges 97 the back plates will pivot about the point 100.

The positions of the heel-breast-receiving shoulders 66 lengthwise of the sole, as above stated, are determined by the position of the guide bar 84 which carries the cutter 64 and which may be adjusted forwardly and rearwardly of the machine upon a carriage 102 through mechanism which will be described later. Since the shoe to be operated upon is positioned lengthwise of itself in the machine by engagement of the rear of the counter portion of the shoe against the back stop 55 which is normally bolted to the main frame, it will be clear that when shoes having different lengths of heel seats are fitted, the crease plates 52, the front edges 70 of which terminate substantially at the breast line of the sole, must be adjusted forwardly and rearwardly of the sole to the same extent as the guide bar and that the cutter will cooperate with the forward parts of the upper surfaces of the crease plates in making the shoulder-forming cuts.

In order to provide for the forward and rearward adjustments of crease plates 52, each of the crease plates comprises in addition to the back plates 98 an elongated side plate 104 shaped and positioned to enter the sides of the rand crease of the shoe (Fig. 4). The inside edges 106 of the side plates 104 engage corresponding outside faces 108 of the back plates 98 and at all times form with the back plates a substantially U-shaped support. Each of the side plates 104 is screwed to a slide arm 110 movable in a guideway 112 of one of the arcuate plates 94, in which guideway it is held by a top plate 114 which may be formed integral with the top part 88 of the bed plate 86. In order to insure that the inner edges of the crease plates 52 will be

held up against the under side of the top plate 114, a V-shaped spring 116 (Figs. 3 and 4) supported by the main frame and having an upward thrust is positioned under 5 the crease plates.

Mechanism for opening and closing crease plates

The mechanism for swinging the crease 10 plates 52 toward and away from each other into and out of engagement with the rand crease of a shoe mounted upon the work support after the former has been moved rearwardly of the machine to the position shown 15 in Fig. 3, and for effecting corresponding 76, is somewhat similar to that disclosed in United States Letters Patent No. 1,834,083, granted December 1, 1931, on an application filed in the 20 name of Harrie A. Ballard. This mechanism comprises a hand lever 118 (Fig. 3) secured to the right end (Fig. 1) of a transversely extending rod 120 supported for rotation in a bearing of the main frame and keyed to an 25 upwardly extending lever 122 (Fig. 3) pivotally secured at its upper end to a slide 124 guided along a slot 126 (Fig. 4) of a rearwardly extending arm 128 having at its rear end a bifurcated portion 130 (Fig. 3) which 30 straddles a block 132 and is connected thereto through a pin 134, the block 132 being universally mounted upon the end of a back lever 136 pivoted at 138 (Fig. 4) to the main frame. The slide 124 is normally held in its rearward 35 position in the slot 126 by a strong spring 140 the forward end of which is connected to an upstanding post 142 carried by the slide 124 and the rear end of which is connected to a lug 144 carried by the block 132. The tension of the spring 140 may be 40 changed by a screw 146 carried by the block 132 and arranged to move the lug 144 along the block. Carried by and pivotally mounted on the back lever 136 is an equalizing bar 148 45 each of the ends of which is pivotally secured to a forwardly extending link 150 having a recess for receiving a pin 152 carried by its respective arcuate plate 94. It will be clear 50 that as the hand lever 118 is moved downwardly, the back lever 136 will swing forwardly of the machine and through the links 150 the crease plates will be moved around the arcuate flanges 97 in such a manner that 55 the rand-crease-entering edges of crease plates 52 will be brought into contact with the rand crease of the shoe and that as the hand lever is raised the sole entering portions of the crease plates will be spread apart.

The connection between the upstanding lever 122 and the back lever 136 is such that upon downward movement of the hand lever and until the crease plates 52 are in their closed positions, the slide 124 remains at the rear end of the slot 126 after which, and as 60 the operator continues to move the hand le-

ver 118 downwardly thereby swinging a depending lever 154 (Fig. 3) rearwardly of the machine about the shaft 120 to raise the shoe support against the bottom of the crease plates as described and claimed in the above-mentioned application for Letters Patent Serial No. 287,429, the slide 124 continues to move forwardly along the slot 125 and to flex the spring 140, the rear end of which is held stationary by the block 132. After the sole of the shoe has been fitted and as the hand lever 118 is raised, the pressure against the crease plates by the shoe 38 is released and the crease plates 52 will remain stationary until the slide 124 reaches the rear end of the slot 126 at which time and upon continued upward movement of the hand lever 118 the crease plates will start to separate.

In the illustrated machine, as already indicated, the sole of the shoe is not centralized in the machine by the contacting of the crease plates with the lines of the sole attaching stitches which usually extend rearwardly of the heel-breast line of the sole but instead the movement of each of the crease plates toward the central plane of the machine is limited by its corresponding centralizing member 54, the equalizing bar 148 serving to permit one of the crease plates to continue its movement toward the central plane of the machine after the opposite crease plate has been stopped by its corresponding centralizing member.

Shoe support and operating mechanism therefor 100

Since the mechanism for operating the shoe support 38 is clearly described and claimed in said United States Letters Patent No. 1,837,399, it will be sufficient briefly to 105 describe this mechanism. In order positively to raise the shoe support 38 for forcing the overlusted portion of the shoe against the bottom of the crease plates as above described, the hollow post 44 carries a pair of 110 diametrically arranged rolls 156 (Figs. 1 and 3) constructed and arranged for engagement with a pivotally mounted cam member 157 which may be swung rearwardly of the machine by a link 158, the forward 115 end of which is pivoted to the cam member 157 and the rear portion of which is connected by a pin-and-slot connection 160 to the depending lever 154. The lever 154 is fulcrumed upon the rod 120 and is mounted 120 for movement with the rod through a depending segment arm 162 keyed to the rod 120 and having an arcuate slot 164 for receiving a clamp screw 166 carried by the depending lever 154 and serving to lock the segment arm 162 and the depending lever together.

In presenting to the machine the heel end of an inverted shoe upon a last mounted upon the last pin 40, the operator swings the work 130

support 38 rearwardly of the machine and at the same time depresses the hollow post 44 against the spring 50 so that the crease plates 52, which have been initially located in a 5 suitable position, slightly overlap the overlasted counter portion of the shoe, the spring 50 carried by the hollow post 44 at the same time tending to force the shoe against the bottom of the crease plates 52 upon rearward 10 movement of the shoe. Upon continued movement of the shoe rearwardly of the machine through mechanism which will later be described in detail, the shoe is centralized by the centralizing members 54, which may also 15 be referred to as centralizing and clamping members, after which it is positioned lengthwise in the machine by the back gage or stop 55. When the machine has been positioned, the operator moves the hand lever 118 20 downwardly and through the above-described mechanism causes the shoe support 38 to be raised upwardly by the cam member 157, the degree of upward force of the shoe against the crease plates being determined by 25 the tension in a spring 168, the opposite ends of which are connected to the depending lever 154 and the cam member 157. The degree of force with which the shoe presses against the bottom of the crease plates 52 may be varied 30 by changing the clamped position of the depending lever 154 relatively to the depending segment arm 162 through the clamp screw 166, which may be adjusted along the arcuate slot 164. In order to lock the shoe in the machine during the fitting operation, the hand lever 118 and the cam members 157 are provided with pawl-and-ratchet members 170 and 172, respectively, provision being made 35 for tripping the pawls of each of the mechanisms at the end of the heel-seat-fitting operation to release the shoe preparatory to removing the shoe from the machine.

Work centralizing mechanism

45 In order to centralize the sole of the shoe in the machine, the illustrated machine is provided with the above-mentioned centralizing and clamping members 54 (Fig. 8) mounted for equal and opposite movement toward and 50 away from each other for engaging the opposite sides of the shoe and with a crotch or V-shaped gage 174 against which the rear of the counter portion of the shoe is engaged. Each of the centralizing members 54 comprises a bell-crank lever 176 geared at 178 to a reverse but corresponding part of the other centralizing member and is pivotally mounted upon a slide 180 which may be moved forwardly and rearwardly of the machine in a 55 guideway 182 which is located centrally of the machine. The slide 180 is normally held forwardly of the machine by a strong spring 184 retained in position by a rod 186 screwed to the slide at 188 and having its front and rear 60 ends in contact with the slide 180 and a frame 65 stop 190 respectively. A pin 192 on the rod 186 is positioned to engage the rear face of the frame stop 190 and thus to limit the forward movement of the slide 180.

70 Mounted for sliding movement in an inner guideway 194 of the slide 180 is another slide 196 having at its forward end the above-mentioned V-shaped gage 174 which cooperates with the centralizing and clamping members 54 for positioning the shoe widthwise in the 75 machine. The slide 196 is normally held forwardly on its guideway 194 by a spring 198 weaker than the spring 184 and surrounding a pin 200, the forward end of which is screwed to the rear end of the slide and the 80 rear end of which is received within a recess 202 of the slide 180. The forward movement of the slide 196 in its guideway 194 is limited by a stud 204 carried by the slide 196 and constructed and arranged for reception 85 in a slot 206 formed in the right bell-crank lever 176 (Fig. 8). The arrangement is such that, when the shoe upon the support is moved rearwardly of the machine and is slightly depressed so that when the overlasted heel portion of the shoe engages the under sides of the forward edge portion of the partially closed crease plates 52, pressure of the rear of the counter portion of the shoe against the V-shaped gage 174 will move the slide 90 rearwardly in its guideway 194 and will compress the spring 198 while the stud 204 carried by the slide 196 and operating within the slot 206 will cause the centralizing members 100 154 to close in upon and to clamp the sides of the shoe upper just forwardly of the breast line 70 of the sole and underneath the crease plates 52. The V-shaped gage 174 and the centralizing or clamping members 105 54, therefore, cooperate to position the shoe widthwise in the machine. Upon contact of the centralizing or clamping members 54 with the shoe, the slides 180 and 196 are locked 110 for movement together and move rearwardly of the machine against the pressure of a strong spring 184 until the rear counter portion of the shoe engages the back stop 55 for positioning the shoe lengthwise of itself in the machine.

115 As above stated, it is important that the median plane of the sole of the shoe positioned in the machine shall lie in the median plane of the machine in order properly to trim the sole for receiving the heel. It will be noted, as illustrated in Fig. 10, that the outer or little-toe side 208 of the counter portion of the shoe is located slightly nearer to the median plane 210 of the sole than is the inner or great-toe side 212 of the counter portion. Moreover, it will be noted that a plane tangent to the outer counter portion 208 at the point of contact of one of the centralizing members with that portion is less inclined to the median plane 210 than a plane tangent to the inner counter portion 212 where the op- 120 125 130 135 140 145 150 155 160 165 170 175 180 185 190 195 200 205 210 215 220 225 230 235 240 245 250 255 260 265 270 275 280 285 290 295 300

posite centralizing member engages that portion. The centralizing or clamping members 54 are normally positioned as above described at equal and opposite distances from the central plane of the machine and if the shoe-contacting portions of these members were positively constrained for unyielding equal and opposite movement upon engagement with the shoe, a central point 214 located between the points of contact, such as indicated by reference numerals 210, 212, would lie in the central vertical plane of the machine and the median plane 210 of the sole would therefore lie to one side or the other of the central plane of the machine, depending upon whether a right or left shoe were being operated upon in the machine.

In order to move the shoe so that the median plane 210 of its sole will lie in the central plane of the machine when operating upon either right or left shoes, each of the centralizing or clamping members 54 is provided with an arm 216 pivotally mounted at 218 (Fig. 9) upon its corresponding bell-crank lever 176 to permit it to swing in a vertical plane relatively to that member, but normally held in position as an extension of the bell-crank lever 176 in the position shown in Fig. 9 by leaf springs 220 secured to the bell-crank lever 176 and engaging the top and bottom faces, respectively, of the arms 216. Each of the arms 216 at its forward end is constructed and arranged universally to support a short stem 222 having an enlarged end portion 224 provided with a convex surface 226 constructed and arranged for engaging the counter portions 208 and 212, respectively, of the shoe, the stem 222 being normally held disposed at right angles to the inside vertical face 228 of the arm 216 by a coiled spring 230, the ends of which engage the face 228 and the enlarged end portion 224. Each of the stems 222, which may be referred to as having a mushroom shape and which serves as a "feeler," has its convex heel-contacting surface 226 so shaped as to rock or to tilt upon the convex counter portions 208 or 212 of the shoe with which it contacts until the stem 222 assumes a position substantially normal to a plane tangent to the counter portion of the shoe at the point of contact.

It has been found, when the centralizing or clamping members 54 contact with the inner and outer counter portions 208 and 212 of the shoe as illustrated in Fig. 10, that as the stems 222 tilt to assume positions normal to their respective planes of tangency the arms 216 are slightly raised and pivot about their respective axes 218, the arm which contacts with the inner exterior counter portion 212 rising much higher than the arm which engages the outside exterior counter portion 208 of the shoe. Since the clamping members are geared together for

equal and opposite movement, it will be understood that, when the stems 222 tilt to positions such as illustrated in Fig. 10, the point 214 located midway between the points of contact of the convex surfaces 226 with the shoe will move to the left of the median plane of the machine a distance indicated by reference numeral 232. When a left shoe is positioned in the machine, the relative positions of the arms 216 and their respective rods at opposite sides of the shoe will be reversed and the central point 214 located between the points of contact of the convex surfaces 226 with the shoe will then be located to the right of the median plane of the machine for a distance corresponding to the distance indicated by reference numeral 232. By tilting one or the other of the stems 222, the point 232 may be shifted to the left or to the right of the central plane of the machine in order that the shoe may be moved so that its median plane lies in the central plane of the machine when operating upon right or left shoes, thereby centralizing the soles of the shoes in the machine. The form of the shoe-contacting surfaces and proportion of the parts of the heel-clamping members, as illustrated in the drawings, have been found satisfactory for usual conditions. It will be clear, however, that the stem may be enlarged to suit special conditions and that the proportions of the parts of the clamping members may be changed without departing from the invention herein disclosed.

In order to limit the movement of each of the crease plates 52 toward the other crease plate, each of the arms 216 is provided with a stop screw 233 which may be adjustably set relatively to the arm by a lock nut 235 and which is engaged by depending portions 237 (Fig. 1) of the crease plates 52.

Mechanism for supporting and guiding back cutter

The cutter shaft 58, which at all times is disposed in perpendicular relation to the crease plates 52 (Figs. 1 and 3) and which is moved in a horseshoe-shaped path for reducing the heel portion of the sole by a bevel cut such as illustrated in Fig. 12, is supported by mechanism somewhat similar to that described and claimed in the above-mentioned United States Letters Patent No. 1,661,391, filed in the name of W. C. Stewart and as also disclosed in said United States Letters Patent No. 1,837,399. This mechanism comprises a table 234 consisting of spaced, parallelly disposed top, middle and lower plates 259, 236 and 238, respectively, secured together and mounted for movement forwardly and rearwardly of the machine in guideways 239 formed in the inside faces of the lateral sides of the machine frame in order to move the back cutter 56 forwardly of the machine.

to an operative position or to move the cutter to an inoperative position such as illustrated in Fig. 3. The back cutter 56 remains in its rearward position while the cutter 64 is operating to form the heel-breast-receiving shoulders 66. The forward movement of the table 234 in the guideways 239 is limited by a stop 240 (Fig. 1) and the rearward movement of the table 234 is limited by engagement of the rear end of the table with an extension 242 of the main frame.

In order to support the cutter shaft 58 and to assure that it is disposed normally to the crease plates 52 during the movement in the horseshoe-shaped path, the machine is provided with an externally threaded sleeve 244 (Fig. 3) mounted upon the shaft 58 and held in predetermined axial relation therewith by upper and lower collars 246 and 248, respectively, secured to the shaft 58. The sleeve 244 is carried in threaded relation with an internally threaded enlarged hub 250 having at its upper portion a circular plate 252 of a size adapted slidably to fit within an opening 254 left between the middle and lower plates 236 and 238, respectively, of the table 234. The arrangement is such that the enlarged hub 250, through the circular plate 252, supports the sleeve 244 which in turn rotatively supports the cutter shaft 58. A recessed portion 256 at the forward central portion of the table 234 is sufficiently large and of a shape to permit the shaft 58 to be guided in a horseshoe-shaped path through mechanism which will now be described.

Mounted in a circular recess 258 in the upper face of the top plate 259 screwed to the upper plate 236 of the table 234 are a pair of overlapping arcuate plates or templets 76, each having a groove 264 (Figs. 3 and 5) shaped and arranged to be received by an arcuate tongue portion 266 of the top plate 259 and arranged for arcuate adjustment toward and away from each other in the circular recess 258. Each of the templets 76 has a portion of reduced thickness which overlaps a reversed but correspondingly reduced part of the other plate. The plates or templets 76 are cut away at their forward central portions to form a U-shaped portion 268 and are provided with the horseshoe shaped guideway 78 constructed and arranged to receive cam rolls 272 attached to and depending from a circular plate 274 which is rotatably mounted in a correspondingly shaped opening of a cutter-operating plate 276 and which is provided with a circular opening of a size suitable for receiving the sleeve 244 mounted upon the cutter shaft 58. The cutter-operating plate 278 is provided with an operating arm 280 and is slidably mounted for movement over the top plate 259 of the table 254 and is arranged to move the cam rolls 272 carried by the circular plate 274 around the horseshoe-shaped guideway 78,

the circular plate, of course, turning relatively to the operating plate 278 during this movement and causing the cutter shaft 58 to move in a horseshoe-shaped path for the purpose of forming the reduced heel-seat portion or tongue 60 on the sole located upon the crease plate 52. The cutter-operating plate 278 is fulcrumed for movement about a pin 282 (Fig. 2) carried by an operating lever 284 pivoted at 286 to the top plate 259, the arrangement being such that the operating arm 280 thus moves the work in moving the cutter in the horseshoe-shaped path, the lever 284 being mainly used for assisting the operating arm 280 in moving around dead-center.

Instead of mounting a gear-carrying housing 288, through which the cutter is rotated and which will later be described, upon the cutter-operating plate, such as is illustrated in said United States Letters Patent No. 1,837,399, it has been found, because of the substantial turning movement of the cutter-operating plate 276 as above described, that in adapting the parts of the machine disclosed in said patent to the herein-described structure it is advantageous to mount the gear-carrying housing 288 (Fig. 1) upon a separate top plate 290 (Fig. 2) in order to limit, by the use of an arcuate groove 292 through the pin 282, the angular swing of the gear-carrying housing 288 during the heel-seat fitting operation. By utilizing the mechanism above described, the cutter 56 may be moved in a horse-shoe shaped path to form tongues 60 having very little width, without the necessity of thinning down and therefore impairing the strength of the cutter guiding elements.

The table 234 may be moved forwardly or rearwardly of the machine by a hand lever 294 positioned at the upper right-hand side of the machine (Figs. 1 and 2) and secured to a rock shaft 294 extending through the frame of the machine and to which is secured an arm 298 (Fig. 3) connected to a rearwardly extending link 300 having near its rear end a slot 302 which is of a size suitable for receiving a pin 304 carried by a depending boss 306 of the table 234. When the table 234 is in its rearward position, the pin 304 engages the front portion of the slot because of the pull of a strong spring 308, the front end of which is connected to the lever 300 and the rear end of which is attached to the pin 304. When the hand lever 294 is swung forwardly of the machine, the lever 300, through the spring 308, carries the table 234 forwardly until it engages the stop 240 (Fig. 1) and upon continued forward swinging movement of the hand lever 294 the spring 308 yields until a latch 310 carried by the lever moves into a notch 312 of the

main frame for holding the hand lever 294 in its forward position.

Mechanism for adjusting templets

5 As above explained, the templets 76 are adjustable about the arcuate tongue 266 and for each degree of adjustment of the crease plates 52 about the arcuate flanges 97 there is a corresponding degree of adjustment of 10 the templets. Since the crease plates 52 are set by the stop screws 233, which, when the shoe is positioned in the machine, are located at substantially equal distances from the median plane of the sole and at opposite sides 15 of the sole, the crease plates in their operative positions will be located at substantially equal distances from the median plane of the sole.

The mechanism for effecting an adjustment 20 of the templets 76 corresponding to the adjustment of the crease plates 52 will now be described. Pivoted to each of the templets 76 at 313 (Fig. 2) and extending rearwardly of the machine are a pair of levers 314 25 pivotally secured at a common point 316 to an arm 318 mounted for forward and rearward swinging movement about a pivot pin 320 in threaded engagement with a lug 322 (Fig. 7) carried by the table 234. The levers 314 are normally urged forwardly of the 30 machine by a spring 324, the rear portion of which is secured to the end of the arm 318 and the forward end of which is secured to a screw 326 mounted upon the top plate 259 of the table 234. Located beneath the arm 318 and also fulcrumed about the pin 320 is a lower arm 328, which is normally rigidly held in its forward position for movement with the arm 318 through a block 330. 35 The block 330 includes a cam 332 carried at the lower end of a rod 334 pivotally mounted for swinging movement in the arm 318 and having a handle 336 which may be set in the position illustrated in Fig. 2 or may be 40 swung to a position such as shown in dotted lines 338 for moving the lower arm 328 rearwardly of the machine in relation to the arm 318. The reason for causing the lower arm 328 to be moved rearwardly relatively to the 45 arm 318 will be presently explained. Extending downwardly from the lower arm is a lug 340 (Fig. 7) which carries at its lower end a bolt 342 extending forwardly and rearwardly of the machine and is constructed and 50 arranged upon movement of the table 234 forwardly of the machine to engage an upstanding lug 344 mounted upon the crease plate operating back lever 136 (Fig. 4). The bolt 342, which carries a lock nut 346, may 55 be adjusted in the depending lug 340 so that when the table 234 is in its forward position the bolt 342, upon engagement with the upstanding lug 344, will swing the arm 318 rearwardly against the pressure of a spring 60 324, which normally keeps the templets 260

in closed relation, for opening the templets 76 to a degree corresponding to the degree of spread of the crease plates 52.

When it is desired to change the back cutter 56, the lower arm 328 is moved rearwardly relatively to the arm 318 by swinging the handle 336 to the position outlined in dotted lines 338 (Fig. 2), and after the stop 240 (Fig. 1) has been swung out of its effective position the table 234 is moved forwardly 70 along its guideway 240 for a distance sufficient to permit the operator to remove the cutter 56 and to replace it with a new one through the recessed portion 36 of the bed castings 34. In providing such an arrangement, it will be clear that a dull cutter may 75 readily be replaced by a new cutter without disturbing the adjustment of the bolt 342 which sets the templets in predetermined positions relatively to the crease plates 52.

In order to move the cutter 56 in a horse-shoe-shaped path for reducing the sole to form the tongue 60 (Fig. 12), the operator 80 grips the handles 348 and 350 of the arm 280 and the lever 284, respectively, and moves the circular plate 274 guided by its cam rolls 272 around the guideway 270. The forward movement of the cutter during this operation is limited by a plate 352 carried by the guide 85 bar 84 and with which the sleeve 244 engages. The construction of the plate 352 and its supporting mechanism will later be described in detail.

When the table 234 is moved from its forward position to its rearward position or vice versa, it is desirable to prevent the cutter which extends below the top plate 114 (Fig. 4) from striking the top plate. Accordingly, provision is made for locating the cutter in a centralized position in order that the cutter will ride lengthwise of the machine in a recess portion 354 of the top plate 114 when the table is moving forwardly or rearwardly. This is accomplished by providing a depending roll 356 carried by the operating arm 280 and adapted to ride in a groove 358 formed in a plate 360 (Fig. 2) screwed to the upper right-hand part of the machine frame and having a wide throat for expediting the guiding of the roll 356 into the groove 358 during the rearward movement of the table 234.

Mechanism for effecting heightwise adjustment of back cutter

The back cutter 56 in moving in the horse-shoe-shaped path just clears the crease plates 52 and should be accurately set heightwise relatively to the plates. For this purpose the externally threaded sleeve 244 mounted on the cutter shaft 58 and secured against axial movement relatively to the cutter shaft 58 by the collars 246 and 248 carries a spur gear 362 (Fig. 3) which meshes with a worm 364 keyed to a pin 366 rotatably mounted in the 125 130

circular plate 252 and having an adjusting head 368 located in a recess in the peripheral portion of the circular plate 252. Rotation of the pin 366 causes the sleeve 244 to be raised or lowered relatively to the enlarged hub 250. This causes the cutter 56 to be raised or lowered relatively to the crease plates 52. In order to lock the sleeve 244 and the enlarged hub 250 together after heightwise adjustment has been effected, the circular plate 252 carries a pin 370 having at its rear end a recessed portion 372 which may be moved forwardly of the machine through a screw 374 for frictionally engaging the rear part of the recessed portion 372 with the sleeve 244.

Surrounding the cutter 56 (Figs. 1 and 3) is a holddown 376 having the general form of a truncated cone and similar to a corresponding holddown disclosed in said United States Letters Patent No. 1,837,399. The holddown 376 is normally urged downwardly by a spiral spring 378 (Fig. 3), the top end of which engages a nut 380 in threaded relation with the sleeve 44, and which has its downward displacement limited, when out of operative position, by a pin 382 which passes through the holddown 376 and engages within a vertical slot (not shown) formed in the lower end of the sleeve 244. When the table 234 is moved forwardly of the machine into operative position, the conical surface of the holddown rides over the sole of the positioned shoe and during the sole-trimming operation of the cutter presses against the sole and prevents the same from being displaced by the cutter.

Heel gage mechanism

The mechanism for operating the carriage 102 which supports the guide bar 84 for movement forwardly and rearwardly of the machine is similar to corresponding mechanism disclosed in the United States Letters Patent No. 1,661,391 above mentioned and is also similar to mechanism disclosed in said United States Letters Patent No. 1,837,399 and comprises an internally threaded boss 384 (Fig. 6) of the carriage 102 receiving an externally threaded screw 386 having at its forward end a style index head 388. Passing through an internally bored portion of the screw 386 is a screw 390, the forward end of which is rotatably secured in a forwardly extending bracket 392 of the machine frame, the screw having at its forward end a size index head 394. The construction and operation of both of these index heads 388 and 394 are described in said United States Letters Patent No. 1,661,391 and both of these indices of the heads may be used, if desired, for positioning mechanism by which heel-breast-receiving shoulders 66 are formed on the sole of the positioned shoe. In the illustrated machine

as in the machine disclosed in said United States Letters Patent No. 1,837,399, however, the lengthwise position of the heel-breast shoulder-forming cutter 64 is preferably determined by gaging from the heel 82 itself rather than by setting the cutter in accordance with numbers marked on the index heads 388 and 394. Accordingly, the style dial 388 of the illustrated machine may be and usually is rendered inoperative by securing the screw 386 against movement in the boss 384 by the use of a thumb screw 396 carried by the boss 384 and the end of which may be clamped against the screw 386. The screw 390 and its size index head 394, however, may be used to move the carriage 102 lengthwise of the machine to a position determined by the heel 82 in the heel gage.

The heel gage 80 consists of a plate 398 secured to the carriage 102 and upon which the heel which is to be attached to the shoe, or a heel like that heel, is placed, attaching-face down, as shown in Figs. 2, 4 and 6. Extending immediately above the surface is a crotched plate 400 adjustably secured to the main frame and shaped to engage the rear portion of the heel positioned attaching-face down upon the plate 398. If the shoes to be operated on are to receive Cuban heels, the breast of the heel on the plate 398 is engaged by a breast plate 402 which may be moved rearwardly of the machine toward the crotched gage and into engagement with the breast of the heel by turning the screw 390.

The breast plate 402 is hinged to the table 404 so that it may be swung forwardly into inoperative position to uncover a shoulder 406 integral with the plate 398 and serving as a breast gage when the machine is operating upon shoes which are to receive Louis heels. The reason for these two gages will be explained later. The crotched plate 400 and the back stop 55 are so initially adjusted when the heel is positioned as illustrated in Figs. 2, 4 and 6 in the heel gage that the cutter 64 which also moves forwardly and rearwardly with the plate 398 will be so located lengthwise of the positioned shoe as to form in the sole of the shoe heel-breast-receiving shoulders 66 which will engage the breast of the heel when the heel is properly positioned upon the shoe.

Mechanism for adjusting the guide bar 84 relatively to the carriage 102

The guide bar 84 is normally rigidly secured with relation to the carriage 102 by means of a T-shaped bracket 408 having in its upper surface a slot in which the guide bar is screwed as indicated by reference numeral 410, and a lug 412 clamped to the T-shaped bracket by bolts 414 and to the carriage 102 by bolts 416 and 418. In order to set the guide bar so that it is disposed substantially perpendicular to the median plane of the

machine, the T-shaped bracket is pivoted for adjustment relatively to the lug upon a stud 420 (Fig. 1) carried by the forward part of the lug 412. In order to position the upper face of the guide bar parallel with the crease plates 52, the lug 412 in turn is pivotally adjustable about the bolt 418, the lug 412 being provided with an arcuate recess (not shown) for receiving the bolt 418. In addition to the above-described adjusting mechanism and in order to assist in effecting the above-mentioned adjustment of the guide bar, the lug 412 is provided with a screw 422 and the T-shaped bracket is also provided with screws 424 and 426 which, through their respective lock nuts, may be used for properly adjusting the guide bar 84 and for retaining the same and the carriage 102 in their relative adjusted positions.

The guide bar 84 is supported at its right end through a lug 428 (Fig. 15) of a casing 430 screwed to the right end of the guide bar 84 and carrying a roller 432 which is mounted for forward and rearward movement in a guideway 434 (Fig. 3). After the guide bar 84 has been properly positioned by the mechanism above described, the guideway 434 is positioned to a horizontal level which will accommodate the roller 432 by moving the guideway along a vertical slide 436 (Fig. 2), the slide then being clamped to the machine frame by a bolt 438.

Heel-breast shoulder-forming mechanism

The mechanism for controlling the movement of the cutter 64 which forms the heel-breast-receiving shoulders 66 will now be described. The guide bar 84 which is rectangular in cross-section and is somewhat similar to a corresponding guide bar of the machine disclosed in said United States Letters Patent No. 1,837,399 is adjustably secured through the above-described mechanism to the carriage 102, the position of which forwardly and rearwardly of the machine is determined by the length of a heel 82 in the heel-measuring gage 80 as already explained. The guide bar 84 is spaced from and extends transversely across the sole of the shoe positioned in the machine and the marginal portion of the heel seat of the sole of which is positioned upon the crease plates 52. Mounted for sliding movement upon the guide bar 84 in a rectilinear path is a carriage 440 having at its rearward portion a vertically disposed notched guideway 442 in which a yoke 444 is mounted for movement in a path perpendicular to the sole of the positioned shoe along the guideway 442 as the carriage 440 is moved transversely across the sole. It is through the yoke 440 that the cutter 64 is raised as it is moved across the sole thereby winging out the fillets 68 so that a cross-section along the heel-breast line of the completely fitted sole approximates a cross-sec-

tion taken along a line such as 446 (Fig. 12) of the tongue and also forming shoulders 66, each of which has the full thickness of the sole from the sole edge to the edge of the tongue and which gradually decreases in height from the edge of the tongue until it reaches a point 450 (Fig. 13) at the tread face of the sole. The point at which the cutter begins to raise may be varied and is controlled by the position of the crease plates as will later be described in detail. The yoke 444 is provided with a U-shaped tongue 452 (Fig. 15) constructed and arranged to be received in a correspondingly shaped slot 454 in a slide 456 and through which, as will later appear, the cutter 64 carried by a cutter housing 458 is moved heightwise of the sole as it is moved widthwise thereof. A cutter-carrying block 460, rectangular in cross-section, is formed integral with the cutter-carrying housing 458 and is secured to the slide 456 through a screw 462 which is in threaded relation with the block 460 and is rotatably secured to the slide 456 by a depending disk 464 keyed to the screw 462 and constructed and arranged to enter a cylindrical recess 466 at the top of the block 460. The cutter housing 457, as illustrated in Fig. 15, carries mechanism for operating the cutter 64.

The block 460 is slidably mounted for movement perpendicular to the sole in a correspondingly shaped guideway of a bracket 468 having an arm which is T-shaped in cross-section (Fig. 1) and is supported for movement lengthwise of the sole in a correspondingly shaped guideway of the carriage 440.

When forming heel-breast-receiving shoulders for Cuban heels, the cutter is moved simultaneously lengthwise of as well as heightwise of the sole as it is moved transversely across the sole, thereby forming a heel-breast-receiving abutment which has substantially the same transverse curvature as the breast of a Cuban heel. It will be clear that as the yoke 444 is moved in a path disposed perpendicularly to the sole, the movement lengthwise of the sole is imparted to the block 460 through the slide 466 screwed thereto and as the bracket 468 is moved lengthwise of the sole the block 460 and the slide 466 will move lengthwise of the sole relatively to the yoke 444 and to the carriage 440.

In order to impart a heightwise movement to the yoke 444 relatively to the carriage 440, the latter is provided with a lever 472 (Figs. 14 and 16), one end of which carries a pin 474 pivotally secured in the carriage 440 and the other end of which is pivotally secured at 476 to the yoke 444. At the opposite side of the lever 472 and at its central portion is a cam roll 478 constructed and arranged to engage within a cam way 480

(Figs. 14 and 16) positioned in the guide bar 84. The cam roll 478 rides in the raised portion 482 of the cam way 480 as the carriage 440 is moved transversely of the sole and raises the yoke 444 and through the above-described mechanism will also raise the cutter-carrying block 460 and the cutter 64.

In order to move the cutter lengthwise of the sole as the carriage 440 moves transversely of the sole and thus to form an abutment comprising shoulders 66, each of which is curved in the plane of the sole, the arm 470 of the bracket 468 may, at the option of the operator, be secured to a slide 484 (Fig. 14) mounted in a correspondingly shaped slot in the top portion of the arm 470 and having a cam roll 486 which engages in a cam way 488 located in the bottom portion of the guide bar 84. It will thus be clear that as the carriage 440 is moved across the guide bar 84, the slide 484, through the cam roll 486, will be moved forwardly and rearwardly of the shoe under the control of the cam way 488 which has a curvature corresponding to the shape of the transverse curvature of the breasts of Cuban heels. The arm 470 may be secured to the slide 484 through a latch slide 490 guided in the arm along a guideway 492 by a pin-and-slot connection 494 and mounted for adjustment in two positions determined by the spring-pressed pin 496 which engages either of two notches 498 or 500 located in the forward edge of the latch slide 490. When the pin 496 is in the notch 498, the latch slide 490 lies entirely to the right of the line 503, the right end of the latch slide 490 then engaging a correspondingly shaped slot 502 in the carriage 440 and through which the arm 470 and the carriage 440 are locked together. When the pin 496 engages the notch 500, the left end of the slide engages a correspondingly shaped guideway in the slide 484, thereby locking the arm 470 and the slide 484 for movement lengthwise of the sole upon movement of the carriage transversely across the sole of the shoe. Lengthwise movement of the slide 484 will thus be imparted to the bracket 468 and through the block 460 to the cutter 64, the slide 456 moving relatively to the yoke 444 along the tongue 452 of the yoke 444.

In order to assure that the cam roll 478 will engage with pressure the top face of the cam way 480 and in order to support the cutter housing 458 and the block 460, the machine is provided with a pair of springs 505 (Figs. 14 and 16) located at each side of the cutter housing 458 and each having its upper end attached to the bracket 468 and its lower end attached to the cutter housing 458.

In different sizes of shoes the attaching faces of heels vary in width and since, as already stated, the reduced heel seat portion 65 comprising the tongue 60 should substantial-

ly fill the concavity of the attaching face of the heel, the width of the tongue 60 should be varied in accordance with the width of the heel which is to be attached to the shoe. In order to control the width to which the base of the tongue is trimmed in accordance with the different widths of tongues shaped by the back cutter 56, the cam way 480 comprises two telescopically arranged parts 504 and 506 which, as illustrated in Fig. 15, overlap lengthwise of the guide bar 84 in order to form a continuous roll-engaging cam way and are mounted for adjustment toward and away from each other along a groove 508 in the guide bar through mechanism which will now be described.

Each of the guideway parts 504 and 506 is retained in position by a stud 510 screwed to its respective part and movable lengthwise of the guide bar 84 in a short slot 512 (Fig. 14). A plate 514 screwed to the rear end of the guide bar also assists in retaining the parts 504 and 506 in relative sliding relation and has a top surface which serves as part of the lower surface of the cam way 480 where the parts 504 and 506 of the cam way overlap.

In order to adjust the parts 504 and 506 toward and away from each other, each of these parts is provided at its forward side, as best shown in Figs. 14 and 15, with a cam roll 516 constructed and arranged to fit in a spiral cam way 518 of a barrel cam 520 rotatably mounted in the guide bar through mechanism which will presently be described.

It is desirable that the cutter 64 shall just clear the crease plates when the cam roll 478 engages within the lower parts of the cam way 480. In order, therefore, to make this adjustment preparatory to operating the machine, the screw 462, which secures the slide 456 to the block 460 of the cutter housing 458, may be rotated for raising or lowering the cutter 64 relatively to the crease plates 52, the adjusted relative positions of the slide 456 and the block 460 being maintained by the operation of a spring-pressed pin 522, carried by the slide 456, against a ratchet 524 on the head of the screw 462.

Sole hold-down for shoulder-forming cutter

While forming the heel-breast-receiving shoulders 66 and winging-out the fillets 68 (Figs. 12 and 13), the cutter 64, which moves in a predetermined path across the sole, has at times a tendency to pick up the sole and this will cause the sole to be cut through its full thickness to a point nearer the median plane of the sole than is desired. The cutter is moved from right to left as viewed from the front of the machine (Fig. 1) or from left to right as viewed in Figs. 17 and 18, and rotates in a counterclockwise direction as shown by arrows on Figs. 17 and 18. It will therefore be clear that the sole must

be firmly held against the crease plates 52 to prevent the sole from being picked up by the cutter 64 as the cutter moves from the edge toward the median plane of the sole. It is not necessary to hold down the sole while the cutter illustrated in Figs. 17 and 18 moves from the median plane of the sole to the opposite side of the sole since the cutter during its trimming operation cuts down into the sole and thus by its own action holds the attaching face of the sole against the crease plate.

In order to hold down the sole during the forming of the first shoulder, the machine is provided with a holddown 526 which in the illustrated machine is shown as pivotally mounted upon an axis which substantially coincides with the axis of rotation of the cutter.

The lower face 528 of the holddown is substantially plane and terminates in a sharply curved rear portion 530, it being understood, however, that the forward part of the holddown may be formed slightly convex, lengthwise thereof if preferred, and is constructed and arranged to engage the sole progressively ahead of the cutter thereby pressing the sole tightly against the crease plates 52 and thus preventing the sole from being picked up by the cutter. Since the holddown is pivoted about an axis located above and rearwardly of its point of engagement with the sole and since the sole-engaging surface 528 is so shaped and arranged that all points on the surface are located at a greater distance from the axis about which the holddown 526 is pivoted, than other points rearwardly thereof, it will be clear, since the sole is held rigidly and the cutter is moved in a predetermined path, that the holddown 526 will bear down upon the sole due to frictional drag against the sole. This holddown action may be said to have a friction pawl effect in pressing the sole against the crease plates.

The arrangement of the axis about which the holddown moves is such that the moment about the axis due to the pressure against the sole will always be greater than the moment about said axis due to the frictional drag of the holddown with the sole, in order that the holddown will effectively press down upon the sole without being dragged toward the cutter with such force as to prevent movement of the cutter across the sole. It will, of course, be clear that where the co-efficient of friction between the steel holddown and the leather which is being operated upon is varied, it may be desirable slightly to change the shape of the sole-engaging face of the holddown or the position of the axis about which the holddown is pivotally mounted.

The face 528 of the illustrated holddown is of sufficient width to engage a sole forwardly and rearwardly of the breast line 70 and as the cutter first moves from its inoperative

position toward the sole, the portion 532 (Fig. 17) of the face 528 of the holddown engages the edge portion of the sole and upon further movement of the cutter toward the median plane of the sole the holddown rides up on the sole, as illustrated in Fig. 18, and swings about its axis so that the rear sharply curved end portion 530 of the face 528 is in engagement with the sole. The cutter, as it moves from the edge of the sole to the position illustrated in Fig. 18, just clears the crease plates 52 thereby cutting the entire thickness of the sole and, as it continues its movement toward the median line of the sole, moves heightwise of the sole to diminish the height of that part of the shoulder.

As the holddown moves from its position of engagement with the edge of the sole to the position illustrated in Fig. 18, the frictional drag between the sole and the holddown will decrease in proportion to the pressure against the sole since the coefficient of friction is a constant times the force exerted upon the face of the sole. The moment arm of the frictional drag, however, will decrease faster than the moment arm which works in co-operation with the friction to lift the holddown. By providing, therefore, the greatest moment due to friction at the beginning of the operation, that is, as the cutter first enters the sole, the edge portion of the sole is held down very effectively at the start of the heel-breast shoulder-forming operation. This is very desirable since the greatest tendency of the cutter to pick up the sole takes place when the cutter first enters the sole. The pressure effect of the holddown after the cutter has started effectively to cut the sole and until the cutter starts to rise has been found to be sufficient to prevent the sole from being lifted up and the slightly lessened pressure against the sole after the cutter has started its shoulder-forming cut is desirable since it enables the operator to push the cutter across the sole to form said shoulders with a minimum amount of effort.

From the time the cutter 64 has reached the position illustrated in Fig. 18 and until it reaches the opposite edge of the sole, it is not necessary, as above stated, to press against the sole in order to prevent the same from being displaced by the cutter. In order, therefore, to retain the holddown in raised position away from the sole during this portion of the shoulder-forming operation, the rear part of the holddown 526 is provided with a ratchet 536 which, as the holddown is swung counterclockwise (Figs. 17 and 18) upon movement of the cutter from the edge of the sole to the position illustrated in Fig. 18, engages a pawl 538 pivoted at 540 and normally held against the ratchet by a spring 542. The holddown 526 is held in its raised position by the pawl 538 until just before the cutter 64 arrives back at its starting position at the

extreme right end of the guide bar (Fig. 1), at which time the top portion of the pawl 538 engages a stop (not shown) and this throws the pawl 538 out of contact with the ratchet 536. This permits the holdown 526, acting under the pressure of a spring-pressed plunger 544 (Fig. 19), to swing the holdown 526 toward the crease plates 52 until a shoulder 546 of the holdown engages a portion of the cutter-carrying housing 458.

In order to move the carriage 440 transversely across the sole of the positioned shoe to form the heel-breast-receiving shoulders 66, the carriage 440 is connected by a link 548

(Fig. 1) to a horizontally disposed rack bar 550 mounted for horizontal movement in a guideway of a rack housing 552 and having inclined teeth which mesh with correspondingly inclined teeth of a vertically disposed

rack bar 554 mounted for vertical movement in a rack housing 556. The arrangement is such that upon downward movement of the rack bar 554, the carriage 440 is moved from right to left (Fig. 1) upon the guide bar 84

and upon upward movement of the rack bar 554, the carriage is moved in the opposite direction upon the guide bar. The lower end of the rack bar 554 is connected through a link 558 to a hand lever 560 pivoted at 562 to the machine frame.

In order to adjust the parts 504 and 506 (Fig. 15) of the cam way 480 toward and away from each other for controlling, through the above-described mechanism, the

lift of the cutter 64 and therefore the width of the tongue 60 at its breast line 70, the barrel cam 520 is rotated upon movement of the crease plates 52 toward and away from each other and is set according to the setting of the crease plates.

To position the barrel cam 520 according to the setting of the crease plates 52, the back arm 136 (Figs. 3 and 4), which is controlled by the hand lever 118 the operative position of which depends upon the crease plates 52 with the stops 233 of the arms 216, has pivoted to its outer end a forwardly extending link 564 (Figs. 3 and 4) consisting of two parts pivoted together at 566. The forward portion of the link 564 is

guided for movement in a slot 568 of the machine and the bottom of said portion is provided with a rack 570 which engages a pinion 572 mounted for rotation about a shaft 574. The pinion 572 also meshes with a rack bar 576 guided in a T-shaped groove 578 (Fig. 4) and is connected by an adjusting screw 579 to a horizontally disposed cam way 580. Another rack bar 581, also guided in the T-shaped groove 578, is provided with a roll

583 which engages within the horizontally disposed cam way 580. The rack bar 581 meshes with a pinion 590 which operates a pinion 592 secured to the end of the barrel cam 520. It will be clear that the position of the back arm 136, which is set according to

the position of the crease plates 52, will, through the mechanism above described, determine the width of the tongue at the breast line of the sole. In order initially to adjust the barrel cam 520 relatively to the back arm 136, the horizontally disposed cam way may be adjusted relatively to the rack bar 576 by turning the adjusting screw 579, after which adjustment the horizontally disposed cam way 580 is locked to the rack bar 581 by the lock nut 594.

Adjustment of crease plates lengthwise of machine

The mechanism for moving the crease plates 52 forwardly and rearwardly of the machine, according to the length of the heel seat of the shoe being operated upon, will now be described. The carriage 102, the position of which forwardly and rearwardly of the machine is determined by the length of the heel 82 in the heel gage, is provided at its forward inner end with a stud 596 (Fig. 4) constructed and arranged for engagement with one of two notches 598 or 600 of a style-adjusting lever 602, which is slidably mounted for adjustment in a guideway 604 of an extension of the carriage 102. The rear end of the lever 602 is bolted to a transversely extending arm 606 having arcuate slots 608 for receiving cam rolls 610 carried by the slide arms 110 which are screwed to the elongated side plates 104. The curvature of the slots 608 is such that upon arcuate movement of the crease plates 52 along the arcuate flanges 97 (Fig. 1) there will not be a movement of the elongated side plates 104 in the guideways forwardly or rearwardly of the machine. When the carriage 102, however, is moved forwardly and rearwardly of the machine, this movement, through the lever 602 and the arm 606, is imparted to the elongated side plates 104, the forward edges of which will at all times be so positioned that they will terminate substantially at the breast line 70 of the sole of the shoe being operated upon and which is to receive the heel 82 positioned in the heel gage.

The curved gaging surface of the breast plate 402 which is used in measuring the lengths of Cuban heels is pivotally mounted at 404 as above described and may be swung forwardly of the machine into inoperative position to uncover the shoulder 406 which is constructed and arranged to engage the lip portions of Louis heels. The distance between the gaging surface of the plate 402 and the shoulder 406 is equal to the difference between average lengths of corresponding Louis and Cuban heels. It will be clear that whether the attaching face of a Louis heel is measured between the plate 402 and the forked gage 400 or whether a corresponding Louis heel is measured between the shoulder 406 and the forked gage 400, the position of

the guide bar 84 and, therefore, of the cutter 64 lengthwise of the machine will remain the same. The length of a Louis heel seat is longer than the length of a heel seat of a corresponding Cuban heel and in the illustrated machine this difference is taken care of by causing the cutter 64 to move in the curved path C, E, D or in the straight path C, E (Fig. 20) according as the machine is operating upon Cuban or Louis heel work respectively as will now be explained.

Changing from one style of work to another

As above explained, when forming heel seats for the reception of Louis heels, the arm 470 (Fig. 16), which is formed integral with the bracket 468 through which the cutter 64 is moved lengthwise of the shoe as it moves transversely across the sole of the shoe, is not attached to the slide 484 which carries the cam roll 486 engaging within the cam way 488 of the guide bar 84 but instead the arm 470 is locked to the carriage 440 and moves with the carriage transversely across the sole in a path included in a plane substantially perpendicular to the median plane of the sole and indicated by the reference characters C, E (Fig. 20). When the latch slide 490, however, is in a position such as that illustrated in Fig. 14, the slide 484 and the arm 470 of the bracket 468 are secured for movement together, and movement of the cam roll 486 along its guideway 488 imparts to the cutter 64 a movement along a path the projection of which upon the plane of the sole when operating on Cuban heels is indicated by lines C, D, E. The outlines 612 and 614 of fitted heel seats or tongues for corresponding Cuban and Louis work relatively to the paths of travel of the cutter for these two types of work are also illustrated in Fig. 20, the average difference between the lengths of these two heel seats being indicated by reference numeral 616. It will be clear that this difference should be substantially equal to the difference between the heel-engaging face of the breast gage 402 and the shoulder 406 which engages the forward lip of a Louis heel.

In order to adjust the crease plates 52 lengthwise of the shoe from rearward position F to position F' (Fig. 20), the crease plates 52 may be set in two different positions relatively to the carriage 102 by engaging one of two notches 598 or 600 (Fig. 4) with the stud 596 carried by the carriage 102. It will be clear that when the notch 600 engages the stud 596 the crease plates 52 will be set at position F for Cuban heel work, and when the notch 598 engages the stud 596 the crease plates 52 will be set in their forward position F' for operating upon Louis work. It will, of course, be clear that the operator will also move the latch slide 490 (Fig. 14) so that the pin 496 engages the notch 498 or

the notch 500 according to whether it is desired to have the cutter move transversely of the shoe in a single plane for Louis heel work or to have the cutter move lengthwise of the shoe as it moves transversely across the sole

70

In fitting the heel seats of shoes for the reception of Louis heels, it will be clear that the back cutter 56 in forming the beveled tongue 60 must be moved farther forwardly of the shoe than in the case of fitting a heel seat of a similar shoe for receiving a Cuban heel. The plate 352 already described as

75

limiting the forward movement of the back cutter 56 must, therefore, have its position changed to provide for the additional movement of the back cutter forwardly of the machine for Louis heel work. Accordingly, the plate 352 is pivoted for movement about a pin 618 (Fig. 14) and is supported by a rearwardly extending bracket 620 (Fig. 3) adjustably secured to the guide bar 84. The plate 352 comprises curved and straight cutter-limiting faces 622 and 624, respectively, positioned at unequal distances from the pin 618. The plate 352, as illustrated in Figs. 2 and 14, is set for Cuban work, the curved face 622 being presented rearwardly of the machine. When the machine is adjusted for Louis work, the plate 352 may be conveniently swung about the pin 618 after releasing a latch 626, which engages a notch at the end of the plate so that the straight face 624 may be presented toward the rear portion of the machine. The plate 352 is then conveniently locked in position by engagement of the latch within a notch 628 thereby setting the plate to permit the cutter to move farther forwardly of the machine than when the plate is set for operating on Cuban work.

Tab forming mechanism

Some shoe manufacturers instead of fitting the soles of shoes which are to receive Louis heels, by moving the shoulder-forming cutter 64 in a curved path included in a single plane extending across the sole as above described, prefer to form a tab such as disclosed in the above-mentioned United States Letters Patent No. 1,527,963, filed in the names of Preo and Henne. This tab serves as an abutment under which the lip of the Louis heel may be positioned and has a base of substantial thickness and tapers to a thin end. In order to equip the illustrated machine for this type of work and as disclosed in United States Letters Patent No. 1,661,391, above mentioned, and in said United States Letters Patent No. 1,837,399, the machine herein illustrated is provided with a knife 630 (Fig. 1) having at its inner end an angular tab-cutting blade secured to a bar 631 mounted for reciprocation in a transversely disposed opening in the carriage

110

115

120

125

130

102. In order to hold the sole during the operation of the knife 630, the machine is provided with a holddown presser roll 632 carried by a vertically extending arm 634 pivotally mounted on a forwardly extending lug 636 attached to the bar 631 and normally held against the sole by a spring 638, the upper and lower ends of which are attached to the bar 631 and the arm 634, respectively. 105 The bar 631 may be operated by a foot treadle 640 (Fig. 2) which is pivotally mounted in the lower end of a vertically extending rod 642 connected through a pin 644 to a bell-crank lever 646 fulcrumed on the main frame at 648 and having its upper arm connected to the bar 631 through the link 650. To insure that when the pressure is released from the treadle the bar 631 will move to its 15 inoperative position at the left of the machine, as best shown in Fig. 1, a spring 652 is provided, the lower end of which is attached to the rod 624 and the upper end of which is secured to the main frame. 20 In factories where the shoulder-forming cutter is used for forming the heel-breast-receiving shoulders for Louis heel work, the knife 630 carried by the bar 631 may have its angular relation to the bar changed and may be used to reduce the thickness of the 25 tongue across its entire width in cases where the soles being operated upon are so thick that they do not fit within the attaching face of the heels and, if not trimmed in this manner, would not permit the rims of the 30 heels applied to the shoes to fit snugly against the counter portions of the shoes. 35

Mechanism for driving cutters

The driving mechanism for the shoulder-forming cutter 64 includes a spur gear 654 (Fig. 15) secured to a shaft 656 upon which the cutter is mounted and rotating through a gear 658 a larger gear 660 keyed to a vertically extending shaft 662, all these gears being mounted in the cutter housing 458 which is formed integral with the block 460 and is raised or lowered as above described upon movement of the cutter 66 across the sole. The bracket 468 (Figs. 15 and 16), through 45 which the cutter is moved lengthwise of the positioned shoe upon movement across the guide bar 84, at its rear portion is provided with a pair of spaced horizontally extending flanges comprising upper and lower bearings 664. Trunnioned in the bearings 664 is a gear casing 666 constructed and arranged to receive the vertically extending shaft 662 and carrying a gear 668 splined through the key-and-slot connection 670 to the shaft 662 in order to permit the shaft to move up and down within the gear casing 666 upon movement of the cutter 64 across the sole. The gear 668 meshes with another gear 672 rotatably mounted in the gear casing 666 and keyed to a 50 stub shaft 674 universally mounted relative- 55

ly to a shaft 676 which telescopes with and is splined to another shaft 678 (Fig. 3) universally secured to another stub shaft 680 connected to a drive shaft (not shown) enclosed in the vertically disposed driving column 70 682 at the rear of the machine.

In order to drive the back cutter 54 (Fig. 1), the cutter shaft 58 is provided with a tongue 684 shaped to fit into a slot at the lower end of a vertically disposed shaft 686 to 75 which is keyed a horizontally arranged spur gear 688. Surrounding the gear 692 is a collar 690 which serves as a bearing for a spur gear 692 keyed to the shaft 694 supported for rotation in the collar 690 and operatively connected to the spur gear 688 through another gear 696 also supported for rotation in the collar. The shaft 694 is in telescoped relation with and is splined to a shaft 698 which receives its power from a drive shaft (not 80 shown) encased in a vertical column 682.

Since mechanism for driving the machine is clearly illustrated in said United States Letters Patent No. 1,837,399, it is not believed to be necessary further to describe this driving mechanism. 90

Procedure in fitting heel seat

In order to perform the heel-seat fitting operation by the use of the illustrated machine, the operator first places the inverted shoe, heel away from him, upon the support 38 and then swings the support rearwardly of the machine as he depresses the shoe, the overlasted counter portions of the shoe upper contacting with the bottom faces of the partially closed crease plates 52. As the shoe is moved rearwardly of the machine, the rear of the counter portion of the shoe engages the V-shaped gage 174 and moves the same rearwardly of the machine, thereby swinging the centralizing and clamping members 54 into engagement with opposite sides of the shoe. When the shoe has been centralized, the centralizing members 54 together with the V-shaped gage 174 move rearwardly of the machine as a unit until the rear part of the shoe 100 engages the back stop 55. 105

The operator next swings the hand lever 118 downwardly, thereby moving the crease plates 52 toward each other until they engage the stop screws 233 and, upon continued movement of the hand lever 118 through mechanism above described, the cam members 157 110 are swung rearwardly of the machine to force the shoe against the bottom faces of the crease plates 52, thus holding the shoe firmly in position. It will be clear that as the crease plates 52 are positioned, the templets 76 and the cam parts 504 and 506 respectively (Fig. 15) of the guide bar 84 will also be moved to 115 positions determined by the positions of the crease plates 52.

The shoe having been positioned in the 120

machine in the manner above described, the operator next moves the table 234 forwardly of the machine from its rearward inoperative position by swinging the lever 294 forwardly until the table 234 contacts with the stop 240 (Fig. 1), the table 234 being then locked against rearward movement by the latch 310 which holds the lever 294 in its forward position. The operator then grips the handles 348 and 350 with his right and his left hands, respectively, and moves the rotary back cutters 56 in a horseshoe-shaped path controlled by the guideway 78 of the temples 76, the forward movement of the cutter in 15 the guideway being limited by contact of the sleeve 244 of the cutter shaft 58 with the above-described plate 352. After the tongue portion 60, such as illustrated in Fig. 12, has been shaped, the lever 294 is released to permit the table 234 to be moved again to its rearward position.

The operator then presses down upon the hand lever 560 which causes the rotary cutter 64 to move transversely across the sole, thereby forming the heel-breast-receiving shoulders 66. When the cutter 64 has been brought back to its original position shown in Fig. 1, the operator raises the hand lever 118, thereby opening the crease plates 52 and 30 permitting the shoe to be swung forwardly of the machine upon the support 38, whereupon the fitted shoe is removed from the machine preparatory to fitting another shoe in the machine.

Having thus described my invention, what I claim as new and desire to secure by Letters Patent of the United States is:

1. A heel-seat fitting machine having, in combination, a pair of plates constructed and arranged to engage within the rand crease of a shoe at opposite sides of the shoe, a gage constructed and arranged for engagement with the rear portion of the shoe for positioning the sole of the shoe lengthwise thereupon said plates, said plates being mounted for adjustment lengthwise of the shoe relatively to the gage, and means for so adjusting the crease plates relatively to the gage that when the rear portion of the shoe engages said gage the plates will terminate substantially at the breast line of the sole.

2. A heel-seat fitting machine having, in combination, crease plates movable toward and away from each other and shaped and arranged for engagement within the rand crease of a shoe at opposite sides of the shoe, a gage constructed and arranged for engagement with the rear portion of the shoe thereby positioning the sole of the shoe lengthwise in the machine, and means for adjusting the crease plates relatively to the gage lengthwise of the shoe so that when the rear of the shoe engages said gage, the crease plates will terminate substantially at the breast line of the sole.

3. A heel-seat fitting machine having, in combination, a plate constructed and arranged for engagement within the rand crease of a shoe, a back gage for engaging the rear end of the shoe, a rotary cutter constructed and arranged for movement relatively to the crease plate to form heel-breast-receiving shoulders upon the sole of the shoe, and means for causing relative adjustment of the crease plate and the back gage lengthwise of the shoe, said cutter being mounted to partake of said relative adjustment in order to maintain its position relatively to the crease plate during said adjustment.

4. A heel-seat fitting machine having, in combination, a plate constructed and arranged for positioning between the rear portion of a sole attached to a shoe and the overlusted counter portion of the shoe, a gage against which the rear of the counter portion of the shoe may be engaged for positioning the shoe lengthwise in the machine, a cutter mounted for movement relatively to the plate and constructed and arranged to form heel-breast-receiving shoulders upon the sole of the shoe, and means for adjusting the plate relatively to the gage lengthwise of the shoe to insure that when the rear portion of the shoe engages the gage the crease plate will extend to the breast line of the sole of the shoe but will not extend forwardly thereof.

5. A heel-seat fitting machine having, in combination, crease plates constructed and arranged to be positioned in the rand crease of a shoe at opposite sides of the shoe, a back gage constructed and arranged to engage the rear portion of the shoe thereby positioning the shoe lengthwise with respect to the crease plates, a cutter constructed and arranged to form heel-breast-receiving shoulders upon the sole supported by the crease plates, and measuring means for adjusting the crease plates relatively to the back gage to insure that when the shoe is positioned against the back gage said plates will extend forwardly substantially to the breast line of the sole.

6. A heel-seat fitting machine having, in combination, plates constructed and arranged to engage within the rand crease of a shoe at opposite sides of the shoe, a back gage constructed and arranged to engage the rear portion of the shoe and to position the shoe lengthwise, a cutter constructed and arranged to form heel-breast-receiving shoulders upon the sole of the shoe, and measuring means for adjusting the crease plates and the cutter relatively to the back gage to insure that when the shoe is positioned against the back gage and the plates are engaged within the rand crease of the shoe such plates will extend forwardly to substantially the breast line of the sole.

7. A heel-seat fitting machine having, in combination, a plate constructed and ar-

- ranged for engagement between the rear portion of a sole attached to a shoe and the overlasted counter portion of the shoe upper, a back gage constructed and arranged for engagement with the rear portion of the shoe for limiting the forward position of the plate between the sole and the shoe upper, a cutter constructed and arranged for forming heel-breast-receiving shoulders upon the sole of the shoe, and heel-controlled means for making corresponding adjustments of the cutter and the plate relatively to the back gage in order that in fitting heel seats of different lengths the cutter will cooperate with substantially the same portion of the plate to form said heel-breast-receiving shoulders.
8. A heel-seat fitting machine having, in combination, crease plates constructed and arranged to enter the rand crease of a shoe at opposite sides of the shoe, a back gage against which the rear portion of the shoe may be rested thereby positioning the shoe lengthwise of said plates, a cutter movable across the sole adjacent to the forward portions of the crease plates for forming on the sole of the shoe heel-breast receiving shoulders, and heel-controlled means for adjusting the plates and the cutter lengthwise of the shoe relatively to the back gage in order that when the sole is positioned upon the plates and when the shoe is moved against the back gage the plates will enter the rand crease of the shoe substantially to the breast line of its sole.
9. A heel-seat fitting machine having, in combination, a pair of plates mounted for movement toward and away from each other and constructed and arranged to engage within the rand crease of a shoe at opposite sides of the shoe, a back gage constructed and arranged to engage the rear of the counter portion of the shoe, a cutter constructed and arranged to form heel-breast-receiving shoulders upon the sole of the shoe, and measuring means for adjusting the crease plates and the cutter lengthwise of the shoe relatively to the back gage.
10. A heel-seat fitting machine having, in combination, pivotally mounted crease plates constructed and arranged to swing toward and away from each other for entering the rand crease of a shoe at opposite sides of the shoe, a back gage against which the rear portion of the shoe may be rested for positioning the shoe lengthwise upon said plates, a cutter movable across the sole and adjacent to the forward portions of the crease plates for forming in the sole of a shoe heel-breast-receiving shoulders, and heel-controlled means for adjusting the plates and the cutter lengthwise of the shoe relatively to the back gage in such a manner that when the shoe is positioned upon the plates and is moved against the back gage the plates will

engage the rand crease to substantially the breast line of the sole.

11. A heel-seat fitting machine having, in combination, crease plates mounted for movement toward and away from each other for entering the rand crease of a shoe at opposite sides of the shoe, a back gage constructed and arranged to engage the rear counter portion of the shoe thereby to position the shoe lengthwise, a cutter constructed and arranged to form heel-breast-receiving shoulders upon the sole of the shoe, and measuring means for adjusting the crease plates relatively to the back gage to insure that when the shoe is positioned against the back gage and the plates are engaged within the rand crease of the shoe said plates will extend forwardly to substantially the breast line of the sole.

12. A heel-seat fitting machine having, in combination, a plate constructed and arranged to be positioned between the rear portion of a sole attached to a shoe and the overlasted counter portion of the shoe upper, a back gage for engaging the rear counter portion of the shoe, a heel gage constructed and arranged to measure a heel which is to be attached to the shoe or a heel like that heel, connections between the heel gage and the plate for adjusting the plate relatively to the back gage thereby insuring that when the rear portion of the shoe rests against said back gage the crease plate will terminate substantially at the breast line of the sole of the shoe, and means for adjusting the plate relatively to the heel gage in order to vary the relative positions of the plate and the gage when operating upon shoes which are to receive Louis and Cuban heels respectively.

13. A heel-seat fitting machine having, in combination, a plate constructed and arranged to be positioned between the rear portion of a sole attached to a shoe and an overlasted counter portion of the shoe upper, a back gage for engaging the rear counter portion of the shoe, a heel gage constructed and arranged to measure a heel which is to be attached to the shoe or a heel like that heel, connections between the heel gage and the plate for adjusting the plate relatively to the back gage thereby insuring that when the rear portion of the shoe rests against said back gage the crease plate will terminate substantially at the breast line of the sole of the shoe, a cutter for forming heel-breast-receiving shoulders upon the sole of the shoe, and means for adjusting the plate in two positions relatively to the heel gage and to the cutter in order to vary the relative positions of the plate and the gage and cutter when operating upon shoes which are to receive Louis and Cuban heels respectively.

14. A machine for operating upon shoes having, in combination, crease plates constructed and arranged to enter the rand crease of a shoe, said crease plates comprising a

back plate constructed and arranged to enter the rear portion of the rand crease of the shoe, and a pair of side plates constructed and arranged to enter the side portions of the 5 rand crease of the shoe, said side plates being mounted for adjustment lengthwise of the shoe relatively to the back plate.

15. A heel-seat fitting machine having, in combination, crease plates constructed and arranged to enter the rand crease of a shoe, said crease plates comprising a back plate constructed and arranged to enter the rear portion of the rand crease of the shoe and also a pair of side plates mounted for adjustment 10 toward and away from each other as well as lengthwise of the shoe.

16. A machine for operating upon shoes having, in combination, crease plates constructed and arranged to enter the rand crease 20 of a shoe, said crease plates comprising a pair of back plates mounted for movement toward and away from each other and a pair of side plates movable toward and away from each other with their respective back plates, and also movable relatively to the back plates, 25 and means for trimming the heel portion of the sole of the shoe.

17. A heel-seat fitting machine having, in combination, crease plates mounted for pivotal movement and constructed and arranged to enter the rand crease of a shoe for supporting the sole thereof to be operated thereon, said crease plates comprising pivotally mounted back plates constructed and arranged to enter the rand crease at the rear portion of the shoe and a pair of side plates pivotally mounted for movement with their respective back plates and formed and arranged to enter the rand crease at the sides 35 of the heel portion of the shoe, the side plates being adjustable lengthwise of the shoe relatively to the back plates to insure that the forward edges of the side plates will terminate substantially at the breast line of the 40 sole of a shoe of the size upon which the machine is to operate, and means for trimming the heel portion of the sole for receiving a heel.

18. A heel-seat fitting machine having, in combination, plates mounted for arcuate movement toward and away from each other and comprising portions constructed and arranged to enter the rear part of the rand crease of the shoe and also side plates supported for arcuate movement with the first-named plates and also mounted for adjustment lengthwise of the shoe relatively to said plates, and means for fitting the heel-seat portion of the sole for receiving a heel.

60 19. A heel-seat fitting machine having, in combination, plates mounted for arcuate movement toward and away from each other and comprising heel-engaging portions constructed and arranged to enter the rear part 65 of the rand crease of a shoe and also com-

prising side plates supported for arcuate movement with said plates and mounted for adjustment lengthwise of the shoe relatively to said plates, a gage for measuring the length of the attaching face of a heel of the size which is to be attached to a shoe, mechanism connected to the heel gage for adjusting the side plates lengthwise of the shoe in accordance with the length of the attaching face of the heel, and means for fitting the heel-seat portion of the sole for receiving the heel. 70

15. A machine for operating upon shoes having, in combination, crease plates comprising a back plate having a concave edge portion constructed and arranged to engage within the rand crease of a shoe at the rear portion of the shoe and side plates adjustable lengthwise of the shoe and constructed and arranged to engage within the rand crease of the shoe at opposite sides of the heel portion of the shoe, said side plates having opposed edge portions which with the concave edge portion of the back plate form a substantially continuous U-shaped portion the 80 length of the sides of which may be varied, and means for trimming the sole of the shoe 85 engaged by said crease plates.

21. A heel-seat fitting machine having, in combination, crease plates comprising back plates constructed and arranged for movement toward and away from each other and forming a concave edge portion constructed and arranged to engage within the rand crease at the rear portion of a shoe and also comprising side plates mounted for movement with their respective back plates and for movement lengthwise of the shoe and having opposed edge portions which with the concave edge portion of the back plates 90 form a continuous U-shaped edge portion the length of the sides of which may be varied according to the length of the heel seat 95 to be fitted in the sole of the shoe. 100

22. A heel-seat fitting machine having, in combination, means constructed and arranged to engage the opposite sides of a shoe having a sole attached thereto, a cutter mounted for movement heightwise of the sole of said shoe as it is moved transversely of the shoe and constructed and arranged to form a heel-breast-receiving abutment in the sole, and mechanism controlled by said means for varying the heightwise movement of the cutter in accordance with the width of the shoe which is being operated on. 110

23. A heel-seat fitting machine having, in combination, members constructed and arranged to engage opposite sides of a shoe, a cutter constructed and arranged for movement heightwise of and transversely of the sole of the shoe engaged by said members for forming upon the sole a heel-breast-receiving abutment, and mechanism which is automatic. 125

cally set according to the position of said members and which is constructed and arranged to vary the path of movement of the cutter across the sole for forming sole heel seats of different widths.

24. A heel-seat fitting machine having, in combination, crease plates constructed and arranged to enter the rand crease of a shoe, means for guiding a cutter heightwise of and transversely across the sole of a shoe supported upon said crease plates for forming heel-breast-receiving shoulders in the sole of the shoe, and mechanism connecting the crease plates and said means for varying the path of movement of the cutter to form upon the sole heel seats of different widths.

25. A heel-seat fitting machine having, in combination, movable crease plates constructed and arranged to enter the rand crease of a shoe, a rotary cutter, means for guiding the cutter heightwise of and transversely across the sole of the shoe for forming heel-breast-receiving shoulders in the sole, and mechanism operated by the crease plates for causing said means to vary the path of movement of the cutter as it is moved across the sole.

26. A heel-seat fitting machine having, in combination, members constructed and arranged to engage opposite sides of a shoe, a cutter mounted for movement transversely across the sole of the shoe engaged by said members for forming upon the sole a heel-breast-receiving abutment, a guideway for moving the cutter heightwise of the sole as it moves transversely across the sole, and mechanism for changing the shape of said guideway upon movement of said members thereby varying the path of movement of the cutter across the sole in accordance with the positions of the members.

27. A heel-seat fitting machine having, in combination, crease plates constructed and arranged to enter the rand crease of a shoe, a cutter, means for guiding the cutter heightwise of the sole of the shoe as the cutter is moved transversely across the sole, said means comprising a two-part telescopic cam way which controls the movement of the cutter, and mechanism constructed and arranged to connect the crease plates and the parts of the cam way for varying the shape of the cam way to change the heightwise movement of the cutter as it moves across the sole in accordance with the width of the shoe being operated on.

28. A heel-seat fitting machine having, in combination, crease plates constructed and arranged to enter the rand crease of a shoe, a cutter movable transversely of the sole of the shoe from one edge of the sole to the other, a guideway for moving the cutter heightwise of the sole as it is moved transversely across the sole, and mechanism con-

nected to said crease plates and constructed and arranged to change the shape of the guideway thereby varying the heightwise movement of the cutter as it moves transversely of the sole to form heel seats the widths of which are determined by the crease plates.

29. A heel-seat fitting machine having, in combination, shoe centering members constructed and arranged to engage opposite sides of a shoe, crease plates mounted for movement toward and away from each other and constructed and arranged to enter the rand crease of the shoe to a depth determined by said members, a cutter constructed and arranged for movement transversely of and heightwise of the sole of the shoe positioned by said members for forming upon the sole a heel-breast-receiving abutment, and mechanism controlled by said crease plates and constructed and arranged to vary the path of movement of the cutter across the sole in accordance with the width of the shoe which is being operated on.

30. A heel-seat fitting machine having, in combination, members constructed and arranged to center a shoe by engagement with opposite sides of the shoe upper, crease plates mounted for movement toward and away from each other and constructed and arranged to enter the rand crease of a shoe positioned by said members to a depth determined by said members, a cutter, means for controlling the movement of the cutter transversely across and heightwise of the sole of the shoe supported in said crease plates for forming heel-breast-receiving shoulders in the sole of the shoe, and mechanism connecting the crease plates with said means for varying the path of movement of the cutter as it is moved across the sole of the shoe to form different widths of fitted heel-seat portions of soles of shoes.

31. A heel-seat fitting machine having, in combination, members constructed and arranged to engage opposite sides of a shoe, a rotary cutter, means constructed and arranged to guide the cutter transversely of and heightwise of the sole of a shoe engaged by said members for forming upon the sole a heel-breast-receiving abutment, and mechanism for operatively connecting the members and said means to vary the position at which the cutter moves heightwise of the sole as it moves transversely of the sole.

32. A heel-seat fitting machine having, in combination, crease plates constructed and arranged to enter the rand crease of a shoe, a rotary cutter, means for guiding the cutter transversely across and heightwise of the sole of a shoe supported by said crease plates for forming heel-breast-receiving shoulders in the sole of the shoe and for winging out portions of the sole rearwardly of said shoulders,

and mechanism constructed and arranged to connect the crease plates and the cutter-guiding means for varying the position at which the cutter moves heightwise of the sole as it moves transversely of the sole in accordance with the width of the shoe being operated on.

33. A heel-seat fitting machine having, in combination, crease plates constructed and arranged to enter the rand crease of a shoe, a cutter mounted for movement transversely of and heightwise of the sole of a shoe which rests against said plates to form at opposite sides of a sole a pair of heel-breast-receiving shoulders separated by the full thickness of the sole, an expansible cam way for moving the cutter heightwise of the sole as it moves transversely of the sole, and mechanism connecting the plates with the cam way for changing the shape of said cam way upon movement of the plates to cause the width of the said full thickness formed between the shoulders to vary according to the position of said plates.

34. A heel-seat fitting machine having, in combination, a pair of crease plates constructed and arranged to enter the rand crease of a shoe, a rotary cutter mounted for movement transversely of and heightwise of a shoe the sole of which rests upon said plates to form at opposite sides of the sole a pair of heel-breast-receiving shoulders separated by the full thickness of the sole and for winging-out from the sole material lying rearwardly of the shoulders, a cam way comprising two parts and having a portion constructed and arranged to raise the cutter as it moves transversely of the sole, and mechanism for connecting the plates to corresponding parts of the cam way for elongating the said portion of the cam way thereby varying the width to which the heel seat portion of the sole is reduced in the vicinity of the heel-breast line of the same.

35. A machine for operating upon the soles of shoes having, in combination, sole-supporting plates mounted for movement toward and away from each other, members for positioning the sole supported by the plates widthwise in the machine, means positioned by the members for limiting the movement of the plates toward each other, and a cutter for trimming the sole so supported and positioned.

36. A machine for operating upon the soles of shoes having, in combination, plates constructed and arranged to support the sole of a shoe and mounted for movement toward and away from each other, members for positioning the sole widthwise, stops carried by the members for limiting the movement of the crease plates toward each other, a cutter for trimming the rear portion of the sole for the reception of a heel, and mechanism for varying the path of movement of said

cutter in accordance with the position of the plate as determined by the stops.

37. A machine for operating upon the soles of shoes having, in combination, plates for supporting soles and mounted for movement toward and away from each other, arms for positioning each of the soles supported by the plates widthwise in the machine, stops carried by the arms for limiting the movement of the plates toward each other, cutters movable relatively to the sole for fitting the heel-seat portion of the sole, and mechanisms for varying the paths of movement of the cutters in accordance with the position of the plates as determined by the stops.

38. A heel-seat fitting machine having, in combination, crease plates mounted for movement toward each other for entering the rand crease of a shoe, members constructed and arranged to engage opposite sides of the shoe to position the shoe widthwise, means positioned by said members for limiting the movement of the crease plates toward each other, and means for operating upon the sole of the shoe thus positioned for fitting the heel-seat portion thereof.

39. A heel-seat fitting machine having, in combination, crease plates spaced from each other and mounted for movement toward each other for entering the rand crease of a shoe, means including members constructed and arranged to engage opposite sides of a shoe for centering the sole of the shoe in the machine, a gage for positioning the shoe lengthwise in the machine, stops carried by each of the centering members for limiting the movement of the crease plates toward each other, and a cutter for operating upon the heel-seat portion of the sole to fit said portion for receiving the attaching face of a wood heel.

40. A heel-seat fitting machine having, in combination, crease plates mounted for movement toward each other for entering the rand crease of a shoe, arms constructed and arranged to engage opposite sides of the shoe for positioning the shoe widthwise, stops carried by said arms for limiting the movement of the crease plates toward each other and thereby determining the position of the plates for operating upon that particular size of shoe, a cutter, means for guiding the cutter in a horseshoe-shaped path, and mechanism controlled by the crease plates for changing the shape of said means thereby varying the path of movement of the cutter in accordance with the width of the shoe being operated on.

41. A heel-seat fitting machine having, in combination, crease plates constructed and arranged for movement toward and away from each other for entering the rand crease of a shoe, means including arms constructed and arranged to engage the opposite sides of a shoe for centering the sole of the shoe in

the machine, a gage for positioning the shoe lengthwise in the machine, stops carried by each of the centering arms for limiting the movement of the crease plates toward each other, means including a cutter movable in a path progressively across and heightwise of the sole for fitting the heel-seat portion of the sole, and mechanism for varying the path of movement of the cutter in accordance with the position of the crease plates as determined by said stops.

42. A heel-seat fitting machine having, in combination, crease plates mounted for movement toward each other to enter the rand 15 crease of a shoe, means including members constructed and arranged to engage opposite sides of the shoe in the machine, a gage for positioning the shoe lengthwise in the machine, a stop carried by each of the members 20 for limiting the movement of the crease plates toward each other, a cutter movable in a horseshoe-shaped path around the peripheral portion of the rear part of the shoe to reduce the heel-seat portion of the sole of the shoe, 25 a cutter movable in a path extending across and heightwise of the sole of the shoe, and mechanism for varying the path of movement of each of the cutters as the relative positions of the crease plates are varied.

43. A heel-seat fitting machine having, in combination, crease plates constructed and arranged for movement toward each other for entering the rand crease of a shoe, a cutter, a guideway constraining the cutter to move in a horseshoe-shaped path as it reduces the rear portion of the sole of the shoe engaged by said crease plates, a cutter arranged to form heel-breast-receiving shoulders upon the sole, means including a guideway for controlling the movement of said second-named cutter, and connections between the crease plates and each of the guideways for varying shapes of the guideways and thereby varying the paths of movement of each of the cutters as the crease plates are set in different adjusted positions.

44. A heel-seat fitting machine having, in combination, crease plates mounted for movement toward each other for entering the rand crease of a shoe, a cutter, means including a cam way constraining the cutter to move in a horseshoe-shaped path extending peripherally of the heel seat of a sole of a shoe supported on said crease plates, another cutter, 55 means including a cam way for controlling the second-named cutter as it is moved in a path extending crosswise of and heightwise of the sole, and mechanism connecting the crease plates with said cam ways for causing the shapes of said cam ways to change in accordance with changes of the positions of the crease plates.

45. A heel-seat fitting machine having, in combination, crease plates constructed and arranged for movement toward each other to

enter the rand crease of a shoe, a rotary cutter, means comprising a cam way having a plurality of parts for constraining the cutter for movement in a horseshoe-shaped path extending around the rear portion of the sole of the shoe engaged by said plates, another rotary cutter, means comprising a cam way having a plurality of parts for controlling the second-named cutter as it is moved transversely across and heightwise of the sole of the shoe thereby forming heel-breast-receiving shoulders upon said sole, and connections between the crease plates and said cam ways for adjusting said parts of the respective cam ways relatively to each other to vary the shapes of the cam ways and therefore the paths of movement of each of the cutters.

46. A heel-seat fitting machine having, in combination, crease plates mounted for movement toward each other for entering the rand crease of a shoe, means including members constructed and arranged to engage opposite sides of the shoe in engagement with said crease plates for centering the sole of the shoe in the machine, stops carried by each of the members for limiting the movement of the crease plates toward each other and thereby positioning the plates for operating upon a shoe of a particular size, a cutter, means including a cam way for constraining the cutter to move in a horseshoe-shaped path extending peripherally of the rear part of the sole for reducing said part, another cutter, means including a cam way for controlling the movement of the second-named cutter transversely of and heightwise of the sole, and mechanism connecting the crease plates and the cam ways for causing the shapes of said cam ways to change upon movement of the crease plates.

47. A heel-seat fitting machine having, in combination, crease plates mounted for movement toward each other for entering the rand crease of a shoe, means including arms constructed and arranged to engage opposite sides of the shoe for centering the shoe in the machine, stops carried by each of the arms for limiting the movement of the crease plates toward each other and thereby positioning the plates for operating upon a shoe of a particular size, a rotary back cutter, means including a two-part cam way for constraining the cutter to move in a horseshoe-shaped path extending peripherally of the rear part of the sole for reducing said part, another rotary cutter, means comprising a two-part cam way for controlling the second-named cutter transversely of and heightwise of the shoe thereby forming heel-breast-receiving shoulders upon the sole, and connections between each of the crease plates and its respective cam-way part for adjusting the parts of each of the cam ways relatively to each other for varying the shapes of the cam ways and there- 130

fore the paths of movement of each of the cutters.

48. A shoe-positioning device having, in combination, a stop for positioning a shoe lengthwise in a machine, a movable gage having a portion constructed and arranged for engagement with opposite sides of the rear portion of the shoe, and clamping members mounted for equal and opposite movement and constructed and arranged to engage opposite sides of the shoe upon movement of said gage toward said stop and to cooperate with said gage for positioning the shoe widthwise in the machine, said gage and said members being mounted for movement rearwardly of the shoe after the said shoe has been positioned widthwise and until the rear portion of the shoe engages said stop.

49. A shoe-positioning device having, in combination, a stop for positioning a shoe lengthwise in a machine, a movable gage for engaging opposite sides of the rear of the counter portion of the shoe and normally urged forwardly away from said stop, and clamping members mounted for equal and opposite movement and normally urged away from each other constructed and arranged to engage opposite sides of the shoe upon movement of the gage toward the stop thereby cooperating with the gage to position the shoe widthwise, said gage and said members being mounted for movement toward the stop after the shoe has been positioned widthwise and until the rear portion of the shoe engages said stop.

50. A shoe-positioning device having, in combination, a stop, a slide mounted for movement relatively to said stop, a gage supported for movement upon the slide and constructed and arranged for engagement with opposite sides of the rear of the counter portion of a shoe, and members carried by said slide and mounted for equal and opposite movement toward and away from each other upon relative movement of the gage and the slide for engaging opposite sides of the shoe thereby cooperating with the gage to center the shoe widthwise, said gage and said member being mounted for movement with the slide and against the stop for positioning the shoe lengthwise after the same has been positioned widthwise.

51. A shoe-positioning device having, in combination, a stop, a slide mounted for movement relatively to said stop, a gage supported for movement upon the slide and having a crotch-shaped portion constructed and arranged for engagement with the opposite sides of the rear of the counter portion of a shoe, and clamp members carried by said slide and mounted for opposite and equal pivotal movement upon movement of the gage relatively to the slide to engage opposite sides of the shoe thereby cooperating with the gage to center the shoe widthwise, said

gage and said clamping members being mounted for movement with the slide and against the stop for positioning the shoe lengthwise after the shoe has been positioned widthwise.

52. A shoe-positioning device having in combination, a stop, a slide mounted for movement relatively to the stop, resilient means for normally urging the slide forwardly of the stop, a gage supported for movement both with and relatively to the slide and constructed and arranged for engagement with the rear of the counter portion of a shoe, resilient means for normally urging the gage forwardly of the stop and relatively to the slide, members carried by the slide and mounted for equal and opposite movement for engaging opposite sides of the shoe thereby cooperating with the gage to center the shoe widthwise, and mechanism for operating said members upon movement of the gage relatively to the slide, said first-named resilient means being stronger than said second-named resilient means to permit the gage to be moved rearwardly of the stop and relatively to the slide thereby moving the members into clamping relation with the shoe in order that the shoe may be first centered and then to permit the gage and the members to move rearwardly as a unit thereby moving the laterally positioned shoe against the stop to position the shoe lengthwise.

53. A shoe-positioning device having, in combination, a stop, a slide mounted for movement relatively to the stop, a spring normally urging the slide forwardly of the stop, a gage supported for movement with and relatively to the slide and having a V-shaped portion constructed and arranged for engagement with the opposite sides of the rear of the counter portion of a shoe, a spring urging the gage forwardly of the stop relatively to the slide, pivotally mounted members carried by the slide and geared together for equal and opposite movement into engagement with opposite sides of the shoe and thereby cooperating with the gage to center the shoe widthwise in the machine, and mechanism for operating said members upon movement of the gage relatively to the slide, said first-named spring being stronger than the second-named spring to permit the gage to be moved rearwardly of the stop relatively to the slide and simultaneously to move the members into clamping relation with the shoe thereby centering the shoe and then to permit the gage and the members as a unit to move rearwardly toward the stop thereby moving the laterally positioned shoe against the stop to position the shoe lengthwise.

54. A shoe-positioning device having, in combination, a stop, a slide mounted for rectilinear movement relatively to said stop and having a guideway formed therein, a spring for normally holding the slide in a forward po-

- sition relatively to the stop, a gage supported for movement along said guideway and having a V-shaped portion constructed and arranged for engagement with opposite sides 5 of the rear of the counter portion of a shoe, a spring positioned between the slide and the gage urging the gage forwardly from the stop and relatively to the slide, members carried by the slide geared for equal and opposite movement for engaging opposite sides of the shoe thereby cooperating with the gage to center the shoe widthwise in the machine, and mechanism for operating said members upon movement of the gage along the guideway, 10 said first-named spring being stronger than the second-named spring to permit the gage to be moved rearwardly of the stop and relatively to the slide thereby moving the members into clamping relation to the shoe to 15 center the shoe widthwise and then to permit the gage and the members to move rearwardly as a unit thereby moving the laterally positioned shoe against the stop to position the shoe lengthwise.
- 20 55. A heel-seat fitting machine having, in combination, a movable gage constructed and arranged to engage the opposite sides of the rear of the counter portion of a shoe, clamping members mounted for equal and opposite movement, connections between the gage and the clamping members constructed and arranged to move the clamping members into engagement with opposite sides of the shoe upon movement of said gage, said gage and 25 said members cooperating to position the shoe in the machine, crease plates constructed and arranged to enter the rand crease of the shoe positioned in the machine, and cutters constructed and arranged to trim the rear portion of the sole of the shoe to shape the sole for receiving a heel.
- 30 56. A heel-seat fitting machine having, in combination, a stop for positioning a shoe lengthwise in a machine, a movable gage having a portion constructed and arranged for engagement with opposite sides of the rear portion of the shoe, clamping members mounted for equal and opposite movement and constructed and arranged to engage opposite sides of the shoe upon movement of 35 said gage toward said stop and to cooperate with said gage for positioning the shoe widthwise in the machine, said gage and said members being mounted for movement rearwardly of the machine after the said shoe has been positioned widthwise until the rear portion of the shoe engages said stop, crease plates constructed and arranged to enter the rand crease of the positioned shoe, and cutters constructed and arranged to trim the rear portion of the sole to shape the same for receiving a heel.
- 40 57. A heel-seat fitting machine having, in combination, a stop for positioning a shoe lengthwise in a machine, a movable gage for

engaging opposite sides of the rear counter portion of the shoe and normally urged forwardly away from said stop, clamping members mounted for equal and opposite movement and normally urged away from each other constructed and arranged to engage opposite sides of the shoe upon movement of the gage toward the stop thereby cooperating with the gage to position the shoe widthwise, said gage and said members being mounted for movement toward the stop after the shoe has been positioned widthwise and until the rear portion of the shoe engages said stop, crease plates constructed and arranged to enter the rand crease of the shoe at opposite sides of the shoe, and rotary cutters constructed and arranged to fit the rear portion of the sole for receiving a heel.

58. A centering device having, in combination, members mounted for equal and opposite movement, said members being positioned at equal distances from the central plane of a machine, and arms pivotally mounted upon the members and constructed and arranged to pivot relatively to said members upon contact with a shoe upper positioned in the machine, the degree of such pivotal movement of the arms relatively to the members being determined by the shape of the shoe upper at its point of contact to position the lengthwise median planes of the soles of right and left shoes substantially within said central plane.

59. A centralizing device having, in combination, a pair of members normally equally spaced from a central plane and constrained for equal and opposite movement relatively to said plane and constructed and arranged to center the sole of a shoe on a last by contact with opposite sides of the shoe upper, said members comprising shoe-contacting parts shaped to swing about their points of contact with the shoe to a degree determined by the shape of the portions of the shoe upper engaged by said parts thereby shifting the center line of the sole of the shoe from a position at one side of the central plane of the machine to the central plane in locating a right shoe and shifting the center line of the sole from a position at the other side of the central plane of the machine to the central plane in a left shoe similar to said right shoe.

60. A sole-locating device having, in combination, members mounted for equal and opposite movement toward and away from the central plane of a machine and constructed and arranged to engage the opposite sides of a shoe upper mounted upon a last, each of said members comprising pivotally mounted shoe-engaging arms normally held in a centralized position, said arms being constructed and arranged upon contact with the shoe to assume positions perpendicular to a plane tangent to the surface of the shoe at the points of contact and thus to shift a point midway

between said points of contact to one side or to the other of said central plane according to the shape of the last.

61. A centering device having, in combination, members mounted for equal and opposite positive movement toward and away from a central plane, and arms mounted upon said members and comprising shoe-engaging portions constructed and arranged for contact with a shoe upon movement of the members toward each other, said shoe-engaging portions being mounted for movement relatively to the members about two centers spaced from each other to permit said portions to move relatively to the members and to assume positions controlled by the curvature of the shoe at the points of contact therewith.

62. A shoe-centering device having, in combination, members mounted for equal and opposite positive movement toward and away from a central plane and constructed and arranged to engage opposite sides of a shoe, each of said members comprising a shoe-engaging portion mounted for pivotal movement about three centers disposed at substantial angles to each other and constructed and arranged when in contact with opposite sides of the shoe to rock relatively to the shoe in order to assume positions substantially normal to a plane tangent to the shoe at the points of contact with the shoe.

63. A shoe-centering device having, in combination, members mounted for equal and opposite positive movement toward and away from a central plane and constructed and arranged to engage the opposite sides of a shoe, each of said members comprising a shoe-engaging portion mounted for pivotal movement about three centers disposed substantially at right angles to each other, said members being constructed and arranged to rock, when in contact with the opposite sides of the shoe, relatively to the shoe in order to assume positions substantially normal to planes tangent to the shoe at the points of contact with the shoe.

64. A shoe-centering device having, in combination, members mounted for equal and opposite movement toward and away from a central plane, and arms carried by said members and comprising stems having convex shoe-engaging portions constructed and arranged for contact with a shoe upon movement of the members toward each other, said stems being mounted for movement relatively to the members about two centers disposed at substantial angles to each other and spaced from each other to permit the stems upon contact with the shoe to pivot relatively to the members and to assume positions controlled by the curvature of the shoe at the points of contact therewith.

65. A shoe-centering device having, in combination, shoe-engaging members, and

means constructed and arranged positively to position the shoe-engaging members at opposite sides of and at equal distances from a central plane, said shoe-engaging members being mounted for pivotal movement upon contact with a shoe, the amount of said pivotal movement being controlled by the curvature of the point of contact of the members with the shoe, thereby positioning the shoe-engaging members at different distances from said plane when the shoe is clamped between said members.

66. A centering device having, in combination, members mounted for equal and opposite movement toward and away from a central plane, an arm pivotally secured to each of the members and normally held in a neutral position relatively thereto, a mushroom-shaped member carried by and mounted for movement relatively to each of the arms and normally held in a neutral position relatively to the arm by which it is carried, said mushroom-shaped members upon engaging a shoe placed between the members being arranged to rock thereby assuming positions disposed substantially tangent to the shoe at the points of contact and causing the arms to pivot relatively to said members.

67. A centering device having, in combination, members mounted for equal and opposite positive movement toward and away from a central plane, and an arm pivotally mounted upon each of the members and normally held in a centralized position relatively to the member on which it is mounted, each of the arms carrying a rocker constructed and arranged to tilt relatively to its arm upon contact with the side of a shoe placed between said arms and to cause the arm upon which it is mounted to pivot relatively to the member upon which the arm is mounted, the extent of the tilting of the rocker depending upon the curvature of the shoe at the point of contact and serving to position a point midway between the points of contact of the rockers with the clamped shoe to the right or to the left of said central plane depending upon whether a right shoe or a left shoe is being positioned.

68. A centering device having, in combination, members mounted for equal and opposite positive movement toward and away from a central plane, an arm pivotally mounted upon each of the members and normally held in a centralized position relatively to the member on which it is mounted, a stem supported for universal movement mounted upon each of said arms and having a head formed with a convex surface constructed and arranged to engage a side of a shoe upon a last upon movement of said members toward each other and to tilt relatively to the shoe in order to permit the stem to assume a position substantially nor-

mal to a plane tangent to the shoe at the point of contact, said tilting movement being such as to cause the arm upon which the stem is mounted to pivot relatively to the member upon which the arm is mounted, the degree of tilting of the stem depending upon the curvature of the shoe at the point of contact and serving to position a point midway between the points of contact of the heads of the stem with the shoe to the right or left of said plane depending upon whether a right or a left shoe is being positioned.

69. A heel-seat fitting machine having, in combination, crease plates mounted for movement toward each other for entering the rand crease of a shoe, shoe-engaging members mounted for movement toward and away from the shoe and for equal and opposite movement toward and away from each other, said shoe-engaging members being mounted for pivotal movement upon contact with the shoe the amount of such pivotal movement being controlled by the curvature of the shoe at the point of contact of the members with the shoe for centralizing the sole of the shoe in the machine, stops carried by each of the members for limiting the movement of the crease plates toward each other, and means for trimming the heel-seat portion of the sole to fit the sole for receiving a heel.

70. A device for centering a sole attached to a shoe having, in combination, a slide comprising a crotch-shaped portion for engaging opposite sides of the rear part of the counter portion of a shoe, a pair of members mounted for equal and opposite movement toward and away from the central plane of the machine and constructed and arranged to engage the opposite sides of the upper of the shoe, each of the members carrying pivotally mounted shoe-engaging parts normally held in a centralized position, said parts being constructed and arranged upon contact with the shoe to assume positions perpendicular to a plane tangent to the shoe at the points of contact with the shoe and thus to shift a point midway between said points of contact to one side or to the other of said central plane according to whether the shoe is a right or a left, and mechanism for connecting the slide and the members for positively moving the parts against the sides of the shoe upon movement of said slide thereby to cooperate with the crotch-shaped portion of the slide in centering the shoe widthwise in the machine.

71. A shoe-positioning device having, in combination, a stop for positioning a shoe lengthwise in a machine, a movable gage having a portion constructed and arranged for engagement with opposite sides of the rear part of the counter portion of the shoe, and clamping members mounted for equal and opposite movement and constructed and arranged to engage opposite sides of the shoe

upon movement of said gage toward said stop and to cooperate with said gage for positioning the shoe widthwise in the machine, each of said members comprising a shoe-engaging portion mounted for pivotal movement about three centers disposed at substantial angles to each other and constructed and arranged when in contact with opposite sides of the shoe to rock relatively to the shoe in order to assume a position substantially normal to a plane tangent to the shoe at the point of contact, said gage and said members being mounted for movement rearwardly of the shoe after the shoe has been positioned widthwise until the rear portion of the shoe engages said stop.

72. A heel-seat fitting machine having, in combination, members mounted for equal and opposite movement toward and away from the central plane of a machine and constructed and arranged to engage the opposite sides of a shoe upper mounted upon a last, each of said members comprising pivotally mounted shoe-engaging arms normally held in a centralizing position, said arms being constructed and arranged upon contact with the shoe to assume positions perpendicular to a plane tangent to the surface of the shoe at the points of contact and thus to shift a point midway between said points of contact to one side or to the other of said central plane according to the shape of the last, crease plates constructed and arranged to enter the rand crease of the shoe, and cutters constructed and arranged to trim the rear portions of the sole of the shoe to a shape suitable for receiving a heel.

73. A heel-seat fitting machine having, in combination, a support for a shoe, members mounted for equal and opposite movement toward and away from a central plane, arms comprising shoe-engaging portions constructed and arranged for contact with the shoe upon movement of the members toward each other, said shoe-engaging portions being mounted for movement relatively to the members about two centers spaced from each other to permit said portions to move relatively to said members and to assume positions controlled by the curvature of the shoe at the points of contact, crease plates constructed and arranged to enter the rand crease of the shoe at opposite sides of the shoe, and rotary cutters constructed and arranged to fit the rear portion of the sole of the shoe for receiving a wood heel.

74. A heel-seat fitting machine having, in combination, a jack for supporting a shoe, members constructed and arranged to engage the opposite sides of the shoe, each of said members comprising a shoe-engaging portion mounted for pivotal movement about three centers disposed substantially at right angles to each other, said members being constructed and arranged to rock when in con-

- tant with the opposite sides of the shoe relatively to the shoe in order to assume positions substantially normal to planes tangent to the shoe at the points of contact with the shoe, crease plates constructed and arranged to enter the rand crease of the shoe, and rotary cutters constructed and arranged to trim the rear portion of the sole of the shoe to a shape suitable for receiving a heel.
75. A heel-seat fitting machine having, in combination, a plate constructed and arranged to engage the rand crease of a shoe, templets movable relatively to each other in accordance with the size of the shoe, a horse-shoe-shaped guideway formed in said templets, a member offset from the guideway and having extensions constructed and arranged to engage within said guideway, and a cutter controlled by said member and constructed and arranged for movement peripherally of the rear portion of the sole of said shoe supported by said plate when said member is moved along the guideway.
76. A heel-seat fitting machine having, in combination, crease plates constructed and arranged to enter the rand crease of a shoe, templets movable toward and away from each other, a horseshoe-shaped guideway formed in said templets, a plate carrying cam rolls constructed and arranged to travel within the guideway, and a cutter movable with said plate and constructed and arranged for movement around the rear of the sole portion of the shoe as the plate is moved around said guideway.
77. A heel-seat fitting machine having, in combination, crease plates constructed and arranged for movement toward and away from each other to enter the rand crease of a shoe, templets also arranged for movement toward and away from each other upon movement of said crease plates, a horseshoe-shaped guideway formed in said templets, a plate having extensions constructed and arranged for engagement within said guideway, and a cutter constrained for movement with the plate upon movement of the same along the guideway and thereby moved peripherally of the rear portion of the sole of the shoe.
78. A heel-seat fitting machine having, in combination, pivotally mounted crease plates constructed and arranged for movement into the rand crease of a shoe, pivotally mounted templets movable with the crease plates along an arc corresponding to the arc of movement of said crease plates, a horseshoe-shaped guideway formed in said templets, a plate carrying cam rolls constructed and arranged to travel in said guideway, and a rotary cutter controlled by the plate as the plate moves around said guideway constructed and arranged to trim the marginal portion of the sole of the shoe supported by the crease plates for providing a tongue portion shaped to fit within the attaching face of a heel to be attached to the shoe.
79. A heel-seat fitting machine having, in combination, crease plates constructed and arranged to enter the rand crease of a shoe, templets movable relatively to each other and shaped to form an opening between them, a horseshoe-shaped guideway formed in said templets, a plate having extensions constructed and arranged to travel in said guideway, and a cutter mounted for movement with the plate and arranged to extend through said opening and constructed and arranged to trim the rear portion of the sole of the shoe as the plate moves around the said horseshoe-shaped guideway.
80. A heel-seat fitting machine having, in combination, a plate constructed and arranged to enter the rand crease of a shoe, a horseshoe-shaped guideway, a member carrying a pair of cam rolls constructed and arranged to travel in said guideway and movable around said guideway in a path controlled by said guideway, and a rotary cutter mounted for rotation upon the member and movable therewith in a horseshoe-shaped path thereby reducing the heel-seat portion of the sole of the shoe for the reception of the attaching face of a heel.
81. A heel-seat fitting machine having, in combination, crease plates constructed and arranged to enter the rand crease of a shoe, templets movable relatively to each other and shaped to form an opening between them, a horseshoe-shaped guideway formed in said templets, a plate positioned and having extensions constructed and arranged for engagement within said guideway, to slide over said templets and a rotary cutter mounted for movement with the plate and arranged to extend through said opening for trimming the rear portion of the sole of the shoe supported upon said crease plates as the cutter-moving plate moves around said horseshoe-shaped guideway.
82. A heel-seat fitting machine having, in combination, a plate constructed and arranged to enter the rand crease of a shoe, a templet, a horseshoe-shaped guideway formed in said templet, a circular member having extensions constructed and arranged to travel in said guideway, a cutter mounted upon said member, and a cutter operating arm in which said circular member is mounted and in which the member rotates as the operating arm moves said member around the guideway thereby moving the cutter peripherally of the rear portion of the sole of the shoe.
83. A heel-seat fitting machine having, in combination, crease plates constructed and arranged to enter the rand crease of a shoe, templets movable toward and away from each other, a horseshoe-shaped guideway formed in said templets, a circular plate hav-

ing cam rolls constructed and arranged to travel in the guideway, a cutter movable with the plate, and a cutter operating arm in which the plate is rotatably mounted and 5 rotates as the arm moves the plate controlled by said rolls around the guideway thereby moving the cutter around the rear portion of the shoe.

84. A heel-seat fitting machine having, in 10 combination, crease plates constructed and arranged to enter the rand crease of a shoe, templets movable relatively to each other and shaped to form an opening between them, a horseshoe-shaped guideway formed in said 15 templets, a circular plate having cam rolls constructed and arranged to travel in said guideway, a cutter mounted for movement with the plate and arranged to extend through said opening, an operating arm 20 which carries the plate and in which the plate rotates as the arm moves the plate along the guideway thereby causing the cutter to trim the rear portion of the sole, and operating handles for moving the plate around the 25 guideway.

85. A heel-seat fitting machine having, in combination, means for positioning the sole of a shoe, a cutter, means for guiding the cutter in a path extending transversely of and 30 heightwise of the sole to form upon the sole heel-breast-receiving shoulders lying substantially in a plane and shaped and arranged to engage the projecting lip of a Louis heel, means for moving the cutter lengthwise 35 of the sole as it moves transversely and heightwise of the sole for forming upon the sole heel-breast-receiving shoulders curved in the plane of the sole and shaped and arranged for receiving a Cuban heel, and mechanism controlled by the operator for rendering 40 said last-named means operative or inoperative for forming heel-breast-receiving shoulders for receiving Cuban or Louis heels, respectively.

86. A heel-seat fitting machine having, in combination, means for positioning a shoe having a shoe attached thereto in a machine, a cutter, a guide bar extending transversely across the sole of the shoe, means comprising 45 a cutter-supporting carriage movable upon the guide transversely across the sole from one side of the sole to the other to cause the cutter to form upon the sole heel-breast-receiving shoulders lying in a plane and shaped and arranged for engagement with the projecting lip of the breast of a Louis heel, said bar being provided with a cam way 50 for causing the cutter as it moves transversely across the sole also to move lengthwise of the sole thereby forming a heel-breast-receiving shoulder curved in the plane of the sole and shaped and arranged for engaging the breast of a Cuban heel, and means for rendering the cam way effective or ineffective at the will of the operator for caus-

ing the cutter as it moves from one side of the sole to the other to form heel-breast-receiving shoulders shaped and arranged either to receive the breasts of Cuban or Louis heels, respectively.

87. A heel-seat fitting machine having, in combination, means for positioning a shoe having a sole attached thereto, a rotary cutter, a guide bar extending transversely across the sole of the shoe, means comprising a cutter carriage movable transversely across the sole upon the guide bar to cause the cutter to form upon the sole a heel-breast-receiving shoulder lying in a plane and shaped and arranged for engagement with the projecting 70 lip of the breast of a Louis heel, a cam way carried by the guide bar, a slide provided with a cam roll carried by the carriage and constructed and arranged to travel in said cam way, a bracket movable with the carriage and mounted for movement relatively to the carriage lengthwise of the shoe, a latch for securing the slide to the bracket thereby causing the bracket to move lengthwise of the sole as the carriage moves transversely of 75 the sole to form shoulders curved in the plane of the sole for receiving the breasts of Cuban heels, and a latch-receiving portion formed in the carriage and constructed and arranged to cooperate with the latch to lock the bracket 80 to the carriage thereby preventing the bracket from moving lengthwise of the carriage as the carriage moves across the sole to form shoulders lying in a plane and constructed and arranged to engage the projecting lips 85 of the breasts of Louis heels.

88. A heel-seat fitting machine having, in combination, means for positioning a shoe in a machine, a guide bar provided with a cam groove and extending transversely of 90 and spaced from the sole of the shoe, a rotary cutter, a support for said cutter movable along the bar and comprising an arm arranged to impart to the cutter as it moves along the bar a movement lengthwise of the 95 shoe, a member movable with the cutter support and comprising a cam constructed and arranged to engage within said cam groove, said member being constructed and arranged for movement relatively to the support and lengthwise of the shoe under the control of the cam groove as the support is moved widthwise of the sole, and a slide constructed and arranged to lock the member to the arm for causing the member through the cam to 100 move the cutter lengthwise of the shoe as the cutter moves transversely of the shoe or, when the slide is released, to permit the member and the arm to be moved independently of each other for rendering the member ineffective to impart movement lengthwise of 105 the shoe to the cutter as the cutter moves across the sole.

89. A heel-seat fitting machine having, in combination, means for positioning a shoe in 110

a machine, a guide bar provided with a plurality of cam grooves and extending transversely of the sole of said shoe, a rotary cutter, a carriage movable along the guide bar, a yoke guided in said carriage for movement perpendicular to the sole of the positioned shoe, a casing in which the cutter is rotatably mounted, a slide supported by the yoke and mounted for movement lengthwise of the shoe along the yoke, a screw for adjustably securing the slide and the casing together, and a guide in which the casing is slidably mounted for movement in a direction perpendicular to the plane of the sole, said yoke and said guide being operated by said grooves as the carriage moves transversely of the shoe in directions perpendicular to and lengthwise of the sole of the shoe, respectively, for imparting to the casing and therefore to the cutter a movement heightwise and lengthwise of the sole as the carriage is moved across the sole for forming upon the sole heel-breast-receiving shoulders each of which is curved in the plane of the sole and decreases in height as it approaches the median line of the sole.

90. A heel-seat fitting machine having, in combination, means for supporting the sole of a shoe, a rotary cutter mounted for movement about an axis disposed substantially normal to the plane of said sole and guided for movement around the rear portion of the sole for reducing the rear portion thereof, means comprising a worm and gear for adjusting the cutter toward and away from the sole-supporting means, and means for locking the cutter in adjusted position.

91. A heel-seat fitting machine having, in combination, crease plates for supporting a sole attached to a shoe, a cutter mounted for rotation about an axis disposed substantially normal to the plates, means for supporting the cutter and for guiding the same in a horseshoe-shaped path over the plates to reduce the heel-seat portion of the sole, and means comprising a worm and gear for adjusting the cutter relatively to the crease plates.

92. A heel-seat fitting machine having, in combination, crease plates for supporting a sole attached to a shoe upper, a cutter mounted for rotation about an axis disposed substantially vertical to said plates, a bushing in which the cutter is rotatably mounted and relatively to which the cutter is secured against movement lengthwise of its axis of rotation, an enlarged hub in threaded relation with the bushing and constructed and arranged for movement in a horseshoe-shaped path thereby moving the cutter over the plate peripherally of the sole to reduce the heel-seat portion of the sole, a gear fixed to the bushing, a worm carried by the hub and constructed and arranged to engage said gear for turning the bushing relatively to

the hub thereby adjusting the position of the bushing axially of the cutter relatively to the hub and thus adjusting the cutter relatively to the plates, and means for locking the hub to the bushing.

93. A trimming machine having, in combination, a support for the sole of a shoe, a cutter mounted for movement and constructed and arranged to trim a sole positioned upon said support, and a holddown supported for movement with and ahead of the cutter and pivotally mounted for movement relatively to the cutter about an axis disposed at a substantial angle to the path of movement of the cutter, said holddown being constructed and arranged to press a portion of the sole ahead of the cutter against said support by reason of the frictional drag between the sole and the cutter.

94. A trimming machine having, in combination, a support for the sole of a shoe, a rotary cutter mounted for movement and constructed and arranged to trim a sole positioned upon said support, and a holddown supported for movement with the cutter and positioned ahead of the same and pivotally mounted for movement relatively to the cutter about an axis which coincides substantially with the axis of rotation of the cutter, said holddown being constructed and arranged to press a portion of the sole ahead of the cutter against said support by reason of the frictional drag between the sole and the cutter.

95. A trimming machine having, in combination, means for supporting the sole of a shoe, a cutter mounted for movement relatively to the sole and constructed and arranged to trim the sole, and a holddown supported for movement with the cutter and pivotally mounted for movement about an axis disposed at a substantial angle to the path of movement of the cutter, said holddown being constructed and arranged progressively to press the sole forwardly of the cutter against said sole-supporting means through the frictional drag between the cutter and the sole and also being so shaped and arranged that the moment about the axis upon which the holddown is pivotally mounted due to the pressure against the sole will always be greater than the moment about said axis due to the frictional drag in order that the holddown will effectively press down the sole without binding.

96. A trimming machine having, in combination, means for supporting the sole of a shoe, a cutter mounted for movement and constructed and arranged to trim the sole, a pivotally mounted holddown supported for movement with the cutter and having a sole-engaging face constructed and arranged progressively to press the portion of the sole forwardly of the cutter against said supporting means through frictional drag with the

sole and to be raised relatively to the cutter due to the pressure of the sole as the cutter moves past the sole, the area of contact of the face with said sole moving rearwardly of said face as the depth of the cut in the sole increases.

97. A heel-seat fitting machine having, in combination, crease plates for entering the rand crease of a shoe thereby to support the sole of the shoe, a rotary cutter constructed and arranged for movement across the sole of the shoe to form heel-breast-receiving shoulders upon the sole, and a holddown supported for movement with the cutter and pivotally mounted for movement about an axis disposed at a substantial angle to the path of movement of the cutter across the sole, said holddown being constructed and arranged progressively to press the sole forwardly of the cutter against the crease plates to a degree determined by the frictional drag between the cutter and the sole.

98. A heel-seat fitting machine having, in combination, crease plates for engaging within the rand crease of a shoe and constructed and arranged to support the sole of the shoe, a rotary cutter constructed and arranged to move widthwise of the sole of the shoe to form heel-breast-receiving shoulders thereon, and a pivoted holddown mounted for movement with the cutter progressively to press upon the portion of the sole forwardly of the cutter by the frictional drag between the cutter and the sole and being so arranged as to be raised relatively to the cutter as the cutter moves from the edge portion of the sole toward the median line of the sole, said holddown being so designed that the moment about the axis upon which the holddown is pivotally mounted due to pressure against the sole will always be greater than the moment about said axis due to the frictional drag of the cutter and the sole in order that the holddown will effectively press the sole without locking the holddown against the sole.

99. A trimming machine having, in combination, means for supporting the sole of a shoe, a cutter constructed and arranged for movement in a defined path for forming heel-breast-receiving shoulders upon the sole, and a holddown comprising a sole-engaging face supported for movement with the cutter and pivotally mounted for movement about an axis disposed at a substantial angle to the path of movement of the cutter across the sole and constructed and arranged progressively to press upon a portion of the sole forwardly of the cutter through the frictional drag between the cutter and the sole, said face having an elongated forward portion constructed and arranged to cause the holddown to ride up the edge of the sole and having a curved rear portion which engages

the sole subsequently during a substantial portion of the heel-seat fitting operation.

100. A trimming machine having, in combination, means for supporting the sole of a shoe, a cutter mounted for movement and constructed and arranged to trim the sole positioned by said means, a pivotally mounted holddown supported for movement with the cutter and having a sole-engaging face constructed and arranged progressively to press the portion of the sole forwardly of the cutter against said positioning means through frictional drag with the sole and also to be raised relatively to the cutter as the depth of the trimming cut in the sole increases, and means for retaining the holddown in its raised position.

101. A heel-seat fitting machine having, in combination, plates for supporting the sole of a shoe, a rotary cutter mounted for movement and constructed and arranged to form heel-breast-receiving shoulders upon the sole positioned upon said plates, a pivotally mounted holddown supported for movement with the cutter and having a sole-engaging face constructed and arranged progressively to press the portion of the sole immediately forward of the cutter against said plates by frictional drag with the sole and to be raised relatively to the cutter as the cutter moves from an edge of the sole to the median line of the sole.

102. A heel-seat fitting machine having, in combination, plates for supporting the sole of a shoe, a rotary cutter mounted for movement and constructed and arranged to form heel-breast-receiving shoulders upon the sole, a pivotally mounted holddown supported for movement with the cutter and also having a sole-engaging face constructed and arranged progressively to press the portion of the sole immediately forward of the cutter against said plates by frictional drag with the sole and to be raised relatively to the cutter as the cutter moves from the edge portion toward the median line of the sole, and a ratchet device for retaining the holddown at its topmost position thereby preventing the hold-down from engagement with the sole during the remainder of the heel-seat fitting operation.

103. A heel-seat fitting machine having, in combination, plates for supporting the sole of a shoe, a rotary cutter constructed and arranged to form heel-breast-receiving shoulders upon the sole of the shoe upon movement of the cutter transversely across the sole, a pivotally mounted holddown supported for movement with the cutter and having a sole-engaging face constructed and arranged progressively to press the portion of the sole forward of the cutter against the plates by frictional drag with the sole and to be raised relatively to the cutter as the cutter moves from the edge portion toward the median plane of

the sole, a member for securing the holddown in its raised position as it is moved away from the sole, resilient means tending to urge the holddown toward the sole, and a release for 5 permitting the holddown to be moved toward the sole under the pressure of said resilient means.

104. A heel-seat fitting machine having, in combination, plates for supporting the sole 10 of a shoe, a rotary cutter constructed and arranged to form heel-breast-receiving shoulders upon the sole of the shoe positioned upon the support upon movement of the cutter transversely across the sole, a pivotally 15 mounted holddown having a ratchet portion and supported for movement with the cutter and also having a sole-engaging face constructed and arranged progressively to press the portion of the sole immediately forward 20 of the cutter against said plates by frictional drag with the sole and to be raised relatively to the cutter as the cutter moves from an edge of the sole toward the median line of 25 the sole, a pawl for engaging the ratchet portion to prevent the holddown as it is raised from swinging back toward the sole, a spring for normally urging the holddown toward the plate, and a stop for swinging the pawl 30 out of engagement with the ratchet to permit the holddown assisted by the spring to move back toward the sole.

105. A heel-seat fitting machine having, in combination, crease plates for engaging the rand crease of a shoe, a rotary cutter constructed and arranged for movement in a defined path across a sole positioned by said 35 plates for forming heel-breast-receiving shoulders upon the sole, and a holddown comprising a sole-engaging portion supported 40 for movement with the cutter and pivotally mounted for movement about an axis disposed at a substantial angle to the path of movement of the cutter across the sole and constructed and arranged progressively to 45 press upon a portion of the sole forwardly of the cutter through the frictional drag between the cutter and the sole, said face having an elongated forward part constructed and arranged to cause the holddown to ride 50 up the edge of the sole and having a curved rear part which engages the sole during a substantial portion of the movement of the cutter from the edge of the sole to the median plane thereof.

55 106. A trimming machine having, in combination, a support for the sole of a shoe, a cutter constructed and arranged to move across a sole positioned upon the support, and a pivotally mounted for movement with the cutter and comprising a sole-engaging face inclined to the plane of the sole and having points along said surface which are nearer the axis about which pivotal movement is effected than points on the surface 60 immediately ahead of said first-named

points, said face being held against the sole to produce a friction-pawl effect to press the sole against the support as the cutter moves across the sole in a fixed path.

107. A trimming machine having, in combination, a support for the sole of a shoe, a cutter constructed and arranged to move across a sole positioned upon the support, and a pivotally mounted for movement with the cutter and comprising a sole-engaging face inclined to the plane of the sole and having points along said surface which are nearer the axis about which pivotal movement is effected than points on the surface 70 immediately ahead of said first-named points, 75 said face being held against the sole by a frictional-pawl action as the cutter moves across the sole in a fixed path, said face also being constructed and arranged to move heightwise of the sole and to have its point 80 of engagement with the sole move rearwardly of the face as it moves toward the median portion of the sole.

108. A heel-seat fitting machine having, in combination, plates constructed and arranged 90 to engage opposite sides of the rand crease of a shoe, a gage arranged for engagement with the rear portion of the shoe to position the same lengthwise in the machine, and mechanism controlled by a heel constructed and 95 arranged to adjust the crease plates lengthwise of the shoe with relation to the gage in order to insure that when the rear portion of the shoe engages said gage the crease plates 100 will terminate substantially at the breast line of the sole of the shoe.

109. A heel-seat fitting machine having, in combination, a plate constructed and arranged for engagement with the rand crease of a shoe, a gage to engage the rear portion 105 of the shoe to position the same lengthwise in the machine, mechanism to form heel breast receiving shoulders upon the sole of the shoe, and means to adjust the crease plate relatively to the gage to insure that when the rear portion of the shoe engages said gage the crease plate will terminate substantially 110 at the breast line of the sole of the shoe, said mechanism being constructed and arranged to partake of said adjustment of the crease plate 115 in order to maintain a predetermined position relatively to the plate for different adjustments of the plates.

In testimony whereof I have signed my 120 name to this specification.

EARL A. BESSOM.

CERTIFICATE OF CORRECTION.

Patent No. 1,902,824.

March 28, 1933.

EARL A. BESSOM.

It is hereby certified that error appears in the printed specification of the above numbered patent requiring correction as follows: Page 3, line 110, for "has" read as; page 4, line 68, for "peparatory" read preparatory; page 5, line 130, strike out the word "in"; page 17, line 67, for "traversely" read transversely; page 30, line 47, claim 86, for "shoe" read sole; and that the said Letters Patent should be read with these corrections therein that the same may conform to the record of the case in the Patent Office.

Signed and sealed this 14th day of November, A. D. 1933.

F. M. Hopkins

(Seal)

Acting Commissioner of Patents.
